UNITED STATES PATENT OFFICE.

CHARLES B. SMITH, OF NEW YORK, N. Y.

TELEPHONE SYSTEM.

SPECIFICATION forming part of Letters Patent No. 727,701, dated May 12, 1903.

Application filed December 31, 1897. Serial No. 664,870. (No model.)

To all whom it may concern:

Be it known that I, CHARLES B. SMITH, a citizen of the United States, and a resident of New York, in the county of New York and State of New York, have invented certain new and useful Improvements in Telephone Systems, of which the following is a specification.

One object of my invention is to provide a telephone system in which a limited number of wires will serve for a larger number of subscribers or telephone instruments. For instance, for one hundred subscribers or telephone instruments I provide such a number of telephoning-circuits as would be equivalent to about the average number of subscribers that would ordinarily be telephoning at the same time—say five circuits.

A further object of the invention is to enable any subscriber on the system to independently or individually call any other subscriber and also to enable the calling subscriber to automatically make direct metallic circuit connections at his telephone instruments with an "idle" or unemployed circuit, so that the called-subscriber's telephone instruments will also make connections with said idle circuit to establish a complete closed metallic circuit between the calling and the called subscribers without the necessity of using a "central office."

In carrying out my invention I provide a telephone system comprising means for selecting and calling or signaling to the desired subscriber direct and means by which an idle or unemployed circuit can be automatically selected and connected through the telephones of the calling and the called subscribers for telephoning purposes. It will be understood that the wires over which the selecting of the desired station and the signaling to the same is done are distinct from the wires used for the telephoning-circuits.

Reference is to be had to the accompanying drawings, forming part hereof, wherein—

Figures 1 and 1^a are diagrammatic views of my improved telephone system, and when considered together they represent four stations or sets of operating devices A B C D, all the devices in stations A and C being in their normal positions and the telephoning devices in stations B and D being shown connected together in a closed metallic circuit

ready for telephoning. Fig. 2 is a front elevation of an instrument provided with the appropriate devices for operating the system complete. Fig. 3 is a side elevation thereof looking from the right in Fig. 2. Fig. 4 is a front elevation of the devices that serve to transmit proper impulses to select desired subscribers' calling instruments and to give a call or signal when said instruments are so selected. Fig. 5 is a side elevation thereof looking from the left in Fig. 4. Fig. 6 is a side elevation thereof looking from the right in Fig. 4, parts being broken away. Fig. 7 is a front elevation of the circuit-changing or circuit-controlling devices which are caused to operate by the devices shown in Figs. 4, 5, and 6 for selecting the station desired, for giving a call or signal thereat, and for returning all the corresponding devices to their normal positions automatically. Fig. 8 is a side elevation thereof looking from the right in Fig. 7. Fig. 9 is a front elevation of the devices that serve to select an idle or unemployed circuit for telephoning, to connect the telephones of a calling and a called subscriber, and to return the circuits to their normal idle conditions. Fig. 10 is a side elevation thereof looking from the left in Fig. 9, part being broken away. Fig. 11 is a horizontal section on the plane of the main shaft shown in Figs. 9 and 10; and Fig. 12 is a plan, projected, of the switching cylinder or drum shown in Figs. 9, 10, and 11.

It will be understood that Figs. 2 to 12, inclusive, illustrate a form of mechanism that I have devised for carrying the system into practice and that said mechanism corresponds in function with the similar parts illustrated diagrammatically in Figs. 1 and 1^a.

I will first describe how one subscriber on the system is enabled to select the calling instruments of the subscriber he desires, to give a call or signal at said instruments, and to return to their normal positions all those instruments that have been operated in giving said call, and I will then explain how the telephone instruments of the calling and the called subscribers are connected together for telephoning and how the corresponding circuits and instruments are returned to their normal positions after the subscribers have finished conversing.

In Figs. 1 and 1^a, A B C D indicate generally subscribers' stations at which are located the various devices that constitute the operative parts of the system, and these devices are connected by appropriate circuits. In the several views similar letters and numerals of reference indicate corresponding parts wherever they occur. In order to accomplish the selecting of the desired station and signaling to the same, I provide a series of four wires, which are apportioned to the calling system. Of these wires one is an independent battery-wire 1, Figs. 1 and 1^a, having opposed batteries 3 3^a at the two ends, such batteries being grounded. This battery-wire is looped into each station, and the current from it is thrown on the other lines to operate the parts connected therewith, as hereinafter described. The other three wires are in reality one wire passing three times through each station. One length of this line is in sections grounded at each station, but adapted by the operation of the appropriate parts to be connected in one continuous line from the first station to the station to be called. The other two lengths are looped into the stations and adapted to have the battery-current thrown on them to operate the mechanisms, as hereinafter described. The wires for telephoning-circuits may be of such number as the necessities of the system may require.

When in this specification I use the term "station," I desire it to be understood as embracing the devices, conductors, contacts, &c., that are apportioned to a subscriber on the system.

The selecting, the calling or signaling, and the restoring devices and circuits may be described as follows:

1 is a conductor or circuit leading through all the stations, and it is shown grounded at both ends at 2 2^a, and near each end said circuit is provided with a battery 3 3^a, as before stated, and the corresponding poles of these batteries are opposed on the circuit, so that the circuit will normally not be charged. At each station on the circuit is located a rotative toothed wheel 4, that is preferably in electrical connection with its supporting-shaft 4^a and the framework 4^b of the device.

4^c is a handle for rotating shaft 4^a and wheel 4. (See Fig. 3.)

The wheel 4 is shown provided with contacts or metal rings 5 5^a 5^b, which are insulated from said wheel and can move therewith. Contacts 6 6^a 6^b, carried by the frame 4^b and insulated therefrom, are in engagement with the contacts 5 5^a 5^b, respectively. (See Figs. 2 and 3.) The contacts 6 in the

several stations are each connected with the line 1, as by a wire 7. Contact or ring 5 is connected, as by a conductor 8, with a switch 9, that is pivotally carried by wheel 4, but insulated therefrom. The switch 9 is adapted when properly moved to engage a contact or pin 10, that is in electrical connection with wheel 4, and thus with the frame 4^b of the

device. (See Fig. 4.) In its normal home position the switch 9 engages a stop or pin 9^a, that is carried by frame 4^b, and thus keeps the switch 9 from engagement with pin or contact 10. (See Figs. 4, 5, 6.) The frame 4^b has an annular series of apertures 11, that are shown located in a ring or plate 12 of frame 4^b, and these apertures are so arranged that when a plug 13, Fig. 3, is placed therein said plug will be in the path of said switch 9 to cause the latter to move into engagement with contact 10. The apertures 11 are all numbered consecutively, and each represents a subscriber or station on the circuit. The frame 4^b (or as shown in diagram in Figs. 1 and 1^a) is connected with a conductor 14, that leads to two contacts or springs 15 16, which respectively form part of a calling or signaling circuit and of a subscriber-selecting circuit. The contacts or springs 15 16 do not coact; but each has a companion contact 15^a 16^a, from which it is normally disengaged, but is adapted to make contact therewith through the action of the wheel 4. The contacts 15^a 16^a are connected with a circuit 17, as by conductors 15^b 16^b. This circuit has portions 17, 17^a, and 17^b leading through all the stations, the portion 17 being normally closed through the switching devices above described, as follows: The contact 6^a is connected with one portion of circuit 17 by a conductor 18, and contact 6^b is also connected with circuit 17 by a conductor 18^a. The contact 5^a is connected by a conductor 19 with a switch 20, that is pivotally carried by wheel 4, but insulated therefrom. The switch 20 is in normal engagement with a pin 21, that is insulated from wheel 4 and connected with contact 5^b by a conductor 21^a. (See Fig. 4.) Thus the normal circuit of line 17 at this portion in each station leads from line 17 through 18, 6^a, 5^a, 19, 20, 21^a, 5^b, contact 6^b, and conductor 18^a back to line 17. Switch 20 is pivotally connected with switch 9 by a link 22, that is insulated from said switches, so that switch 20 will be moved by and with switch 9. It will be understood that when wheel 4 is moved to select a subscriber switch 9 will engage the plug 13, that has been placed in the appropriate aperture 11, so that when switch 9 is moved into engagement with pin 10 (by engaging plug 13) switch 20 will be moved out of engagement with contact 21, thus breaking the normal circuit through line 17 at this part. The teeth 4^x 4^y upon the periphery of wheel 4 are adapted to close and open the circuit through 17 at 16 16^a for the purpose of transmitting an impulse or impulses to select the desired subscriber after the normal circuit through 6^a 6^b, &c., has been broken, (after wheel 4 has been turned to select a subscriber and switch 9 placed in contact with pin 10,) in which case the circuit through the instrument under consideration will be as follows: from grounds 2 and 2^a at the ends of the system through batteries 3 and 3^a and line 1 to the corresponding conductor

7 in the operating-station, thence through contacts 6 5 8, switch 9, pin or contact 10, wheel 4, frame 4^b, conductor 14, spring or contact 16, and its companion contact 16^a (when 16 and 16^a are made to engage) and 16^b to line 17, and thence to portion 17^a of the circuit, on which are located the switching or selecting devices that serve to connect the calling subscriber with the subscriber desired. These selecting devices consist in each station of a cylinder or drum 70, carrying on its surface plates or contacts, such as 45 37 55 32 42. These plates or contacts are of different lengths to suit the duration of contact required in each case. This drum 70 is adapted to be rotated in one direction only, making one forward movement when a magnet 39 attracts its armature 39^a and another forward movement when said armature is retracted by a retractile spring 79. (See Fig. 8.) This operation will be described more fully hereinafter. The rotation of the drum 70 is designed to bring plates or contacts 45, 37, 55, 32, and 42 in contact with springs or contacts arranged to bear upon them at the proper time. These plates or contacts on drum 70 are duplicated eight times on the circumference thereof. (This number may be increased or decreased in proportion to the size of drum and amount of its movement.) In the normal position of drum 70 the relation of these contacts to their contacting springs is as follows: Contact 45 is out of engagement with springs 44 and 46, contact 37 is out of engagement with 35 and 36, contact 55 is out of engagement with springs 54 and 56, contact 32 is in engagement with springs 31 and 31^a, and contact 42 is in engagement with springs 41 and 43. The first forward movement of drum 70 brings one of the contacts 45 into engagement with spring-contacts 44 and 46. None of contacts 37 are by this movement brought into contact with 35 and 36, and neither of the contacts 55 is as yet brought into engagement with 54 and 56; but a contact 32, being a long contact, continues to be in engagement with springs 31 and 31^a. A contact 42 is now out of engagement with 41 and 43. The second forward movement of drum 70, caused by the retraction of spring of armature 39^a, brings contact 45 out of engagement with 44 and 46, contact 37 into engagement with 35 and 36, contact 55 into engagement with 54 and 56, contact 32 out of engagement with 31 and 31^a, and neither of the contacts 42 is in engagement with 41 43. The third forward movement of drum 70, caused by a second closing of armature 39^a, brings contact 37 out of engagement with 35 and 36 and contact 55, which is a long contact, just out of engagement with springs 54 and 56, while the other contacts on the drum are still out of engagement with their respective springs. The fourth movement (last movement) of drum 70, caused by the armature 39^a being again retracted by its spring, brings the contacts to the normal position first described; but it

will be noticed that the springs that are now in engagement with contacts are bearing upon contacts on the drum belonging to a second series of such contacts.

The circuit through 17^a at the first station on a system, as A, normally leads to ground at 30, and throughout the remainder of the stations this circuit is divided or "sectional"— that is to say, it is not a normally closed circuit through all the stations, but has a portion leading from one station to ground 30 in the next station; but this section is normally disconnected from the portion leading into a station from a preceding station, although the portions leading into and from a station are adapted to be connected together in each station. I have denominated this portion of the subscriber-selecting circuit as 17^a through-out, and for convenience of further description I have lettered the portion of this circuit that leads from a station as 17^x and the part where it leads into a station as 17^y. In each station the subscriber-selecting circuit leads from 17^y to the contact or spring 31, that normally engages contact or plate 32, which latter is normally in engagement with contact 31^a, that is connected by a conductor 33 with ground 30 through relay-magnet 34. The subscriber-selecting circuit from the switching devices in a station when wheel 4 has been turned to select a subscriber is as follows: to ground 30 at the first station on a system, as A, from grounds 2 and 2^a, through batteries 3 and 3^a over line 1 to the calling-subscriber's station, as B, thence through conductor 7, contacts 6 5, conductor 8, switch 9, and contact 10, (parts 9 and 10 having been brought into engagement by the movement of wheel 4, causing switch 9 to strike the plug 13, and the normal circuit through 17 having been broken, as before explained,) to wheel 4, thence through contact 16^a (by the action of teeth 4^x of wheel 4) and the conductor 16^b to line 17, thence over line 17 to station A, and through 18, 6^a, 6^b, 19, 21^a, 5^b, 6^b, and 18^a back to 17, (the switch 4, &c., at A not having been moved,) thence along line 17 to 17^a and through its part 17^y to 31, 32, 31^a, and magnet 34 to ground 30, thus energizing said magnet. If any other station on the system farther from A than B had been the calling-station, the circuit would likewise have been through the parts 6^a 6^b, &c., at each station between the calling-station and the first station, as A, to ground thereat, the object being to operate the subscriber-selecting devices at the first station on the line, as A, first and then to operate the corresponding devices at the second station, and so on successively to the desired station; but if station A had been the calling-station the circuit would have led direct from 16 16^a thereat through line 17 to portion 17^a. It will be understood that each time a tooth 4^x of wheel 4 makes the circuit at 16 16^a an impulse will be sent over circuit 17 17^a, &c., the number of such impulses corresponding to the number

of the station called. As the portion 17^a of the subscriber-selecting circuit is divided or sectional in each station, the various grounds 30 in all stations up to the called station are 5 to be broken and the corresponding portions 17^x 17^y of the circuit through 17^a are to be connected to form a through-line between the calling and the called stations. This is accomplished as follows: Conductor 17^y in 10 each station is connected with a spring-contact 35, and the conductor 17^x in each station is connected with a spring-contact 36; but these contacts are normally out of engagement, although, as before stated, they 15 are adapted to be brought into electrical engagement by contact or plate 37. The contact 37 is to be brought into engagement with contacts 35 36 after contact 32 has been moved away from contacts 31 31^a. Thus after contact 32 in a station is moved away from contacts 31 31^a to break ground 30 in that station contact 37 will be brought into engagement with contacts 35 36 in the same station to establish a through-line to the next station, and 20 so on successively in stations that intervene between the first station on the line, as A, and a station to be called. It will be understood that the magnets 34 control the movements of said contacts or plates. For this purpose 25 I have shown a normally open local circuit in each station comprising a contact 38, conductor 38^a, magnet 39, a conductor 40, leading to a wire 27, that includes a battery 28, and a conductor 40^a, leading from wire 27 to 30 an armature 34^a of magnet 34, which armature (or a contact operated thereby) is adapted to close this local circuit by engaging contact 38. Magnet 39 operates the armature 39^a, as before stated. Thus when an impulse 35 is sent through magnet 34 the latter will act through its armature 34^a to close the said local circuit at 34^a 38 to cause contact 32 to move away from contacts 31 31^a to break the normal ground-circuit to 30 in the corresponding 40 station. If a station beyond is desired, contact 37 will be brought into engagement with contacts 35 36 to establish a line from the station being considered to ground 30 in the next station on the circuit, and so on successively to the desired station, in which contact 32 is held under 31 31^a temporarily to enable the bell-circuit to be completed. Means for breaking the line so established and for reestablishing the ground 30 in each 45 station will be explained hereinafter.

With the devices so far described let it be supposed that a subscriber at station B desires to select a subscriber at station D. He first places his plug 13 in the aperture 11 corresponding to station D and then turns his wheel 4 by means of handle 4^c to the left in the drawings until his switch 9 is moved against plug 13, the continued movement of wheel 4 causing switch 9 to turn on its pivot 50 until the pin 10 passes into engagement with said switch 9. The wheel 4 is thereupon returned to the home point either directly by

the operator or by suitable mechanisms, as hereinafter explained. The said movement of switch 9 also moves switch 20 away from 70 the contact 21, and these switches remain so placed until wheel 4 arrives at the home point, where both switches are moved to their normal positions by switch 9 engaging stop 9^a, wheel 4 continuing to move the proper 75 distance. The normal circuit of line 17 through the calling-station is thus broken at 20 21 (through 18, 6^a, 18^a, 6^b) and the batteries 3 and 3^a thrown on line 17 to the left to operate the selecting device at station A, as follows: As wheel 4 moves toward home its teeth 80 4^x make and break the subscriber-selecting circuit at 16 16^a. The first impulse sent over the circuit from batteries 3 and 3^a through line 17 17^a, as before detailed, passes to 85 ground 30 at station A (the first station on the circuit) and causes magnet 34 to close the local circuit through magnet 39. The drum 70, at A, now makes the first movement, before described, bringing contact 45 into engagement with 44 46, contact 32 remaining in engagement with 31 and 31^a and moving contact 42 out of engagement with 41 and 43. The circuit of magnet 34 is now broken at 16 16^a in the calling-station by the action of teeth 90 4^x of wheel 4, whereupon said magnet at station A releases its armature 34^a, causing the local circuit through magnet 39 to be broken at 38. Magnet 39 thereupon releases armature 39^a, and its retractile spring effects the 95 second forward movement of the drum, bringing contacts 32 out of engagement with 31 31^a, thereby breaking off the ground 30 at station A. Contact 45 is now out of engagement with 44 and 46, and contact 37 is brought into 100 engagement with contacts 35 36, whereby two sections of the line are joined together at A, as from 17^y to 35 through 37 and 36 to 17^x, the new line now leading therefrom through 17^y at B to 31, 32, 31^a, 33, through magnet 34, 105 to ground 30 at B. The next impulse and break over the line so formed causes a similar operation of drum 70 at B, breaking off ground 30, and causing two sections of the line 110 17^a to be similarly connected at B. A third impulse has the same effect at C, and thus a line has been established out of the various 115 "sections" through stations A, B, and C direct to ground 30 at D. As D is the station to be called, a through-line to the next station 120 beyond is not formed; but the fourth impulse is held on the line while a call is being given magnet 34 at D, holding its armature attracted. Magnet 39 in consequence holds its armature 39^a closed, keeping contact 32 of drum 125 70 still in engagement with 31 31^a, thus holding ground 30 in station D unbroken. By this impulse contact 45 has been brought into engagement with contacts 44 and 46 and is held there to effect the operation of calling. 130

The manner of sending a call and of holding the circuit complete and of preventing the completion of the circuit through 17^a to the next station (beyond D) is as follows:

The wheel 4 carries a circuit-operating device 23 23^a, that is adapted to make and break connection between the contacts 15 15^a in order to give a call or signal in the desired station 5 and subsequently to restore all the subscriber-selecting instruments that may have been operated to their normal positions. This signaling and instrument-restoring circuit at this part of the system may be traced as follows: from grounds 2 and 2^a at each end of the system through batteries 3 and 3^a and line 1 to conductor 7 in the operating-station, thence through contacts 6 5 8 9 10, wheel 4, frame 4^b, conductor 14, contact 15, its companion contact or spring 15^a, (when they are brought together by the devices 23 23^a, (and the conductor 16^b to line 17, thence along line 17 to the right in the drawings through the various corresponding instruments to the portion 20 17^d of the circuit at the last station on the system, thence over line 17^d through any possible intermediate station to the desired station. The device 23 is a projection or tooth carried by wheel 4, and the device 23^a, is similar, but preferably longer, to produce a closing of the circuit of comparatively long duration, and there is a space 23^b between the teeth or projections 23 23^a to produce a break in the flow of the current. The last 25 tooth, as 4^y, on wheel 4 is longer than the teeth 4^x and is placed in line (laterally) with tooth or projection 23, the arrangement being such that while tooth 4^y (which corresponds to the selected station) holds contacts 30 16 16^a together tooth 23 will hold contacts 15 15^a together to produce the call or signal, and the tooth 4^y will continue to so hold the selecting-line until after projection 23 leaves contact 15^a, whereupon tooth 4^y releases contact 16 and breaks the circuit through the selecting-line. Thereupon projection 23^a acts to again close the circuit through contacts 15 15^a to restore to normal all the subscriber-selecting devices that may have been operated 40 in selecting the desired subscriber, all as more fully explained hereinafter.

The circuit through line 17^d is normally closed in each station and is adapted to be broken and re-formed in two ways, one for calling or signaling and the other for restoring, the arrangement being as follows: In each station for convenience of description the part of line 17^d that leads into a station is numbered 17^s, and the part leading from 55 the station is numbered 17^t. The part 17^s of line 17^d in each station leads to the contact or spring 41, that normally engages the contact or plate 42, which is in normal engagement with the contact 43, that is connected 60 with the appropriate part 17^t of line 17^d. Line 17^d continues from contact 43 in one station through the part 17^s of the line in the next station to contact 41 thereat, and so on through each station, the line being open at 65 the extreme station, as A, on the system. Thus a normal closed line is established in 17^d through all the stations from right to left

in Figs. 1 and 1^a. In each station the contact 44 is connected, as by conductor 44^a, with the part 17^s of line 17^d, and contact 44 is adapted 70 to be engaged by the contact or plate 45, but is normally out of engagement therewith. Contact or plate 45 is also normally out of engagement with but is adapted to engage a contact 46, which is connected by a conductor 47 with ground 48, (or a common return-wire connected with all conductors 47 on the system,) and the conductor 47 includes a magnet 49. Thus when contact 45 in a station is moved into engagement with 75 contacts 44 46 (the arrangement being such that at this time contact 42 will have been moved out of engagement with contacts 41 43, as before explained) the line 17^d in that station will be grounded, the through-line in this 80 station having been broken at 41 42 43, and the new circuit will be as follows: from part 17^s of line 17^d to 44^a, thence through 44, 45, 46, 47, and magnet 49 to ground 48. The circuit so established is for calling or signaling in a 85 selected station, and by preference I utilize a calling instrument 50 on a normally open local circuit in each station that is controlled by the magnet 49. This local circuit is shown as follows: 51 is a contact from which a conductor 52 leads to wire 27, bell or signaling instrument 50 being located on conductor 52. The circuit passes thence through 27, battery 28, and conductor 40^a to a conductor 52^a, that connects with an armature 49^a of magnet 49, 90 which armature or a contact operated thereby is adapted to engage contact 51 to close the local circuit. Thus if while contacts 44, 45, and 46 are in engagement an impulse is sent along line 17^d by the closing of contacts 105 15 15^a a circuit will be established to ground 48 at the station to be called, as follows: from the ground of line 1 and its batteries through said line to the calling-station, as B, thence through conductor 7, contacts 6 and 5, conductor 8, switch 9, contact 10, (with which said switch will be in engagement, as before explained,) wheel 4, frame 4^b, conductor 14, contacts 15 15^a, (which are now held in engagement by presser 23,) to conductor 15^b, to line 110 17, thence along line 17 through any intervening stations to the end of the system, (at the right in Fig. 1^a,) thence to portion 17^d of the line to the selected station D, thence through portion 17^s of the line to conductor 115 44^a, contacts 44 45 46, and conductor 47, through magnet 49 to ground 48. Magnet 49 will now attract its armature 49^a to close the local calling-circuit from 51 through 52^a (including instrument 50) to line 27, through 120 battery 28 to conductor 40^a, thence through 52^a to armature 49^a, (or a contact operated thereby,) back to contact 51. A call or signal will now be given by instrument 50 in the selected station, as D. By preference I utilize 125 this closing of the local bell-circuit to also perform an operation with relation to the telephone-circuits, as hereinafter explained.

It will be understood that the stations are

selected from left to right in Figs. 1 and 1^a through the stations that intervene between the first station and a station to be called and that the contacts 42, 32, 37, and 45 are only 5 moved in selecting a subscriber in the instruments (on the system) that intervene between the first station and the station to be selected and in the latter station sufficiently far to disengage 42 from 41 43 and to engage 45 10 with 44 46, (contact 32, it will be remembered, is still in contact with 31 and 31^a,) whereby line 17^d is left normally closed from the opposite end of the system (on the right in Fig. 1^a) through all the stations to ground 48 at 15 the selected station.

After a call has been given, as explained, the circuits through those instruments that have been operated in selecting a subscriber are to be returned to their normal positions. 20 This may be accomplished as follows: From the conductor 44^a in each station a conductor 53 leads to a contact 54, that is normally out of engagement with but is adapted to be engaged by a contact or plate 55. Contact or 25 plate 55 is also normally out of engagement with but is adapted to engage a contact 56, that is connected by a conductor 57 with the conductor 33, leading to ground 30. Contact 55 is so located that it will engage its contacts 54 56, while contact 37 engages its contacts 35 36; but contact 55 is wider than contact 37, so that it will remain longer in engagement with its contacts 54 56 than contact 37 does with its contacts 35 36. Now after 30 an impulse has been sent over the line 17^d to ground 48 to produce a call, as before explained, the projection or presser 23 on wheel 4 at station B will pass from contact 15^a, and thus cause the latter to break the circuit at 35 15^a, whereupon all the contacts 42 32 55 37 45 will be operated and in such manner that contacts 37 and 55 will be moved, in manner before described as the second movement, into engagement with their respective contacts 35 36 and 54 56, whereupon two sections 40 of line 17^a are joined together, as before explained, and a new ground is formed for line 17^d from 17^s through 53, 54, 56, 57, 33, and 34 to 30 in all stations whose corresponding 45 instruments have been operated. Wheel 4, continuing to move toward the home point, next causes projection 23^a (by pressing 15 15^a together) to send current over the circuit from grounds 2 and 2^a, through batteries 3 50 and 3^a, over line to the calling-station, thence through conductor 7, contacts 6 5, wire 8, switch 9, contact 10, wheel 4, frame 4^b, conductor 14, contacts 15 15^a, and conductor 15^b to line 17, (all at the calling-station,) thence 55 to line 17^d and along the same to the called station, in which the circuit passes from 17^s to 44^a, thence to 53, 54, 55, 56, 33, and through magnet 34 to ground 30. Magnet 34 now closes the before-described local circuit 60 through magnet 39 at 31^a 38, and the armature of magnet 39 thereupon acts to move contacts 42, 32, 55, 37, and 45, whereupon the

circuits through 37 will be broken; but the circuit through 55 will be continued a little longer than through 37 to assure the complete 70 action of magnet 39. Then the circuit through 55 will be finally broken, while at about the same time contact 42 will be brought into engagement with its contacts 41 43 to restore the normal circuit of 17^d through the instrument. Thereupon the current now on the line will travel through all the instruments on the line that may have been operated, performing the same restoring operations in them all. The current being next broken from the 80 line by the passing of projection 23^a from contact 15^a, the set of contacts 42 32 55 37 45 will be given a further movement to finally restore all the circuits to their normal conditions, thus bringing contact 32 into engagement with contacts 31 31^a and leaving contact 42 in engagement with contacts 41 43. It will be understood that these actions take place successively in all the stations that have been operated in reaching a desired station. 90

It is desirable when one subscriber is operating the above-described devices to select and call another subscriber that any other subscriber will be prevented from operating his corresponding instrument, and for this 95 purpose at each station I place a magnet 24 in the line 1; but this magnet is normally shunted from the line as follows: From line 1 on one side of its connection with magnet 24 extends a conductor 24^a, that leads to a 100 contact 24^b, that is in normal engagement with a spring or contact 24^c, and from the contact 24^c extends a conductor 24^d, which joins line 1 on the side of magnet 24 opposite to the connection of conductor 24^a therewith. 105 The wheel 4 carries a stop or presser 25, that holds the contacts 24^b 24^c in engagement when wheel 4 is in its normal home position; but when wheel 4 is moved away from its normal position contacts 24^b 24^c will separate, thus 110 breaking the shunt around the magnet and allowing the battery on line 1 to energize said magnet. Magnet 24 thereupon acts to close a normally open local circuit through a magnet 26 at each station. The local circuit for 115 each magnet 26 is arranged as follows: With one terminal of said magnet is connected a conductor 27, which leads to battery 28, thence to contact 27^a, which is adapted to be engaged by an armature 24^f, belonging to magnet 120 24, and said armature is connected with the other terminal of magnet 26 by a conductor 27^b. The armature 26^a of magnet 26 is adapted to operate a detent or finger 26^b, that is arranged to engage the teeth 4^x on 125 wheel 4 to prevent the corresponding wheel from being turned far from its home point. Thus when the line is being used for calling and a subscriber turns his wheel 4 far enough to disengage his switch 20 from its contact 130 21 the line will be charged from battery 3 or 3^a through the new circuit formed by switch 9 engaging contact 10, and if another subscriber starts to move his wheel 4 he will

immediately break the shunt around his magnet 24, thus allowing the current on line 1 to energize his magnet 24. This magnet 24 will then attract its armature 24^f, thus closing 5 the local circuit 27, 27^a, 24^f, and 27^b through magnet 26, and battery 28 will cause magnet 26 to attract its armature 26^a, which will move detent 26^b in the path of teeth 4^x of wheel 4, and thus block or check the intended 10 movement of wheel 4. By this means all subscribers are prevented from interfering while a calling subscriber is operating his device to select a subscriber and to signal to him; but as soon as wheel 4 of the calling 15 subscriber has reached its home point the stop 9^a will move switches 9 and 20 to their normal positions, thus removing the charge of the current from line 1 to enable any other subscriber to operate his wheel. In Figs. 4 20 and 5 the detent is shown carried independently of armature 26^a and connected therewith by a light spring 26^d, which will act to throw the detent into engagement with teeth 4^x of wheel 4 to prevent forward movement 25 thereof and yet allow said wheel to return to its normal position without interference.

As the several subscriber selecting, calling, and restoring circuits have been described generally, I will now explain the 30 mechanical devices I have illustrated whereby certain changes in the circuits are effected in conjunction with the circuits set forth. In the construction illustrated in Figs. 2, 3, 4, 5, and 6 I have shown a spring 60, that is connected at one end with shaft 4^a of the selecting and calling switching devices, the other end of the spring being connected with the frame 4^b and so arranged that as the wheel 4 is turned to the left in Fig. 4 the spring 60 will 40 be wound, and when the wheel is released said spring will act to return the wheel to zero or the home point. To cause wheel 4 to return to the normal position at the proper speed, I provide a train of gear-wheels having a fan 61 and a main gear 62, loosely hung on shaft 4^a, but having a spring-acting pawl 63 to engage a ratchet-wheel 64, secured on shaft 4^a. With this arrangement as the selecting-wheel 4 is turned in the direction of 45 arrow *a* in Fig. 4 the teeth of the ratchet 64 will slip under the pawl 63; but when said wheel 4 is released the ratchet, acting through pawl 63 and the train of gearing, will cause fan 61 to rotate, and thus retard or regulate 50 the speed of return of wheel 4 to zero to the proper degree.

I will now describe more fully the mechanical devices (shown in Figs. 2 to 6, inclusive) for regulating the impulses sent along the 60 circuits before described, for selecting the desired subscriber, for giving a call, and for returning the parts to their normal positions, as follows: The companion contacts or springs 15 15^a and 16 16^a and 24^b 24^c are shown carried by frame 4^b, but insulated therefrom. In Fig. 4 contacts 15 16 are shown connected by a plate 15^d, and in Figs. 4 and 6 contact

15 is shown capable of being moved into engagement with contact 15^a, while in Figs. 1 and 1^a contact 15^a is arranged to be moved 70 against contact 15. In Figs. 2 to 6 I have shown rocker arms or levers 65 66, that are pivotally carried by a rod or shaft 67 of frame 4^b and independently movable thereon. Arms 65 66 are arranged to operate contacts 16 15, 75 respectively, and they carry insulated points 65^a 66^a, that engage said contacts. At their ends opposite this insulation the arms 65 66 have projections or fingers 65^b 66^b, the projection 65^b being arranged to engage teeth 4^x 80 4^y of wheel 4, while the projection 66^b is adapted to engage the projections 23 23^a and to pass into the space 23^b between the latter. The number of teeth 4^x 4^y on wheel 4 are equal to the number of subscribers on a circuit; but tooth 4^y is longer or wider than the tooth 4^x to produce a longer contact, so as to hold contacts 44 45 46 together in the selected station while a call is being given. There is a long space 4^c on the periphery of wheel 4 90 between tooth 4^y and the first tooth of the series of teeth 4^x. (See Fig. 4.) The projection 65^b of arm 65 normally rests against that side of the first tooth 4^x that faces the tooth 4^y, so that arm 65 will normally be tilted to 95 cause contacts 16 16^a to be normally separated. Arm 66 carries a pin 66^c, that normally rests against frame 4^b to enable contacts 15 15^a to be normally separated, and the outer end of projection 66^b normally lies 100 within the path of the outer surface of projection 23^a. The working sides of projections 65^b 66^b are inclined to enable the projections to ride up on teeth 4^x 4^y and on projections 23 23^a. These projections 23 23^a are shown 105 comprised in a plate having a space 23^b, which plate is secured on the side of wheel 4 in line with rocker-arm 66. The presser 25 is shown in the form of a finger carried by wheel 4, and it may be insulated therefrom or have insulation where it presses contacts 24^b 24^c together, said contacts being normally held in engagement by said presser. The detent 26^b is shown pivotally carried by frame 4^b, as at 26^f. The operative end or point of 110 detent 26^b is inclined in such manner that it can enter between teeth 4^x of wheel 4 and so that it can block the movement of said wheel when the latter is turned in the direction of arrow *a*, Fig. 4, but will permit said teeth to 115 slide over it when the wheel moves in the reverse direction. Switches 9 and 20 are mounted on insulation *b*, carried by wheel 4, so as to move along the face thereof, and link 22 may travel in a recess 22^a in said insulation, 120 Figs. 5 and 6. The insulation *b* carries a pin *b'*, against which switch 9 is pressed when it engages stop or pin 9^a on ring 12, whereby wheel 4 is brought to rest and held at the home position under the influence of spring 60. 125

The devices by which contacts 45, 37, 55, 32, and 42 are carried and operated are illustrated in detail in Figs. 2, 3, 7, and 8 and are arranged as follows: These contacts are

secured upon a drum or cylinder 70, preferably of insulating material, although it may be made of metal and the contacts insulated from it. The said contacts are arranged upon 5 the drum 70 in the relative positions shown in Fig. 7 for controlling their respective circuits at the proper moments. One of each of these contacts 45 37 55 32 42 comprise a complete set, and there may be any desired number 10 of such sets of contacts upon each drum 70. In the arrangements shown provision is made for eight sets of such contacts. The drum 70 is supported by shaft 71, which is journaled in bearings on a frame 72, so that 15 said drum can rotate, or said drum may be mounted loosely on said shaft. To the drum 70 or its shaft 71 is attached a toothed wheel 73, having twice as many teeth 73^a as there are sets of contacts 45 55 32 42. To the frame 20 72 are pivotally connected arms 74 75, which are adapted to oscillate, these arms being shown pivoted at 74^a 75^a to a support or plate 76 of frame 72. The arms 74 75 carry pawls 74^b 75^b, respectively, which pawls are adapted 25 to engage the teeth 73^a of wheel 73. (See Fig. 8.) The arms 74 75 are respectively pivotally connected by links 77 77^a with a lever 78, and the lever 78 is pivotally connected with frame 72, as at 78^a, being shown secured 30 to a shaft 78^b, journaled in bearings carried by frame 72. (See Fig. 7.) The armature 39^a of magnet 39 is connected with lever 78, so that when said armature is attracted by magnet 39 the lever 78 will be turned on its 35 axis to draw links 77 and 77^a. Lever 78 is connected by a spring 79 with frame 72 to act against the attraction of magnet 39, the spring 79 serving to cause lever 78 to push links 77 77^a. The arrangement is such, as 40 shown in Fig. 8, that in the normal positions of the parts the pawls 74^b 75^b will be in engagement with the edges of teeth 73^a. Now when magnet 39 attracts its armature 39^a it will move the upper end of lever 78 outwardly 45 or in the direction of the arrow in Fig. 8, whereupon pawl 74^b will act to turn wheel 73 and drum 70 one step, which is equivalent to a distance moved by half of a tooth 73^a, during which movement pawl 75^b will 50 be drawn into engagement with the edge of a new tooth 73^a, these movements of pawls 74^b 75^b being simultaneously in the same direction, caused by the links 77 77^a drawing arms 74 75 outwardly. As soon as magnet 55 39 is deenergized the spring 79 will draw lever 78 in the reverse direction, whereupon links 77 77^a will push arms 74 75 rearwardly, (or to the right in Fig. 8,) whereupon pawl 75^b will push upon the tooth 73^a, with which 60 it is in engagement, and thereby turn wheel 73 and drum 70 a distance equal to half a tooth 73^a, while at the same time pawl 74^b will be moved into engagement with a new tooth 73^a. The movement thus imparted to 65 wheel 73 by the independent action of pawls 74^b 75^b is equal to the length of a tooth 73^a, so that a complete forward-and-back stroke

of lever 78 by the combined action of magnet 39 and spring 79 drum 70 will be given one complete movement necessary to move contacts 45 37 55 32 42 together a proper distance. In order that the pawls 74^b 75^b will not cause wheel 73 to overthrow, but will bring it to a stop at the proper point, I provide abutments 74^c 75^c, which are adapted to respectively engage the pawls 74^b 75^b when they have been moved by lever 78 the proper distance, and the arrangement is such that the pawl will be jammed between its abutment 74^c or 75^c and the corresponding tooth 73^a of 80 wheel 73 with which it may be in engagement. The action of the foregoing devices for operating drum 70 may be explained in connection with the selecting, calling, and restoring 85 circuits, heretofore described with relation to Figs. 1 and 1^a, as follows: The relative positions of contacts 45, 37, 55, 32, and 42, comprising a set of contacts, are illustrated in diagram in Figs. 1 and 1^a, and the same are 90 clearly shown in Fig. 7 with relation to the respective contacts 46 44 36 35 54 56 31^a 31 41 43, and the drums 70 are shown in their normal positions. Now when a subscriber first turns the handle 4^c of his circuit-controlling 95 wheel 4 switch 9 as it encounters plug 13, that has been placed in an aperture 11, corresponding to the subscriber desired, is moved into engagement with contact 10 to close the subscriber-selecting circuit, and thereupon 100 as wheel 4 is moved back toward its home point by the action of spring 60 the first tooth of said wheel that engages the rocker-arm 65 will close the circuit at 16 16^a, thus sending an impulse to magnet 34 at the first station 105 on the system, as A, which will close the local circuit for the corresponding magnet 39. Magnet 39 now attracts its armature 39^a, which moves lever 78, whereupon pawl 74^b will turn drum 70 a distance equal to half of a tooth 110 73^a, whereupon contact 45 will be brought into engagement with contacts 46 44 to close the circuit for producing a call, contact 42 will be moved away from contacts 41 43 to break the normal restoring-circuit, contact 115 32 will be moved a distance, but will still remain in engagement with contacts 31 31^a to hold the ground-circuit to 30, and contacts 37 and 55 will be moved a distance, but not yet into engagement with their respective contacts 35 36 and 54 56. Now if a call is to be sent to this station (the first station on the circuit) the long tooth 4^y of wheel 4 will hold the circuit closed to ground 30 and projection 23 will operate rocker-arm 66 to close the call-producing circuit at 15 15^a, whereupon current traversing contacts 44 45 46 to ground 48 will cause magnet 49 to close the local circuit for the signaling instrument 50. A continued movement of wheel 4 causes rocker-arm 66 to 120 move off projection 23, thus breaking the call-producing circuit, and immediately thereafter rocker-arm 65 will move off tooth 4^y, thus breaking the subscriber-selecting circuit.

Magnet 39 is now deenergized, whereupon spring 79 will draw lever 78 and cause pawl 75^b to push wheel 73 the distance of half a tooth 73^a, whereupon the contacts on drum 70 will be moved so as to disengage contact 45 from contacts 44 46 to cause contact 37 to engage contacts 35 36, whereby two sections of line 17^a are joined together to cause contact 55 to engage contacts 54 56 and to cause contact 32 to leave contacts 31 31^a to break the operating-circuit through magnet 34, contact 42 not yet being drawn into engagement with contacts 41 43. Projection 23^a will now reach rocker-arm 66 and again close the circuit through 15 15^a, whereupon current will traverse line 17 toward the right in Figs. 1, 1^a to line 17^d, and thence through all the intervening stations to the called station on the circuit A, whereupon the circuit will find ground from 17^s through 53, 54, 55, 56, 57, 33, 34, to ground 30, thus causing magnet 34 to again close the local circuit of magnet 39. Magnet 39 now attracts its armature 39^a and moves lever 78 outwardly, thus again turning drum 70 the distance of half a tooth 73^a, whereupon contact 37 will move from contacts 35 36 to break the sections of line 17^a, and immediately thereafter contact 55 will move from contacts 54 56 to break the restoring-circuit, thus causing magnet 39 to become deenergized, whereupon spring 79 will draw lever 78 to turn drum 70 the distance of half a tooth 73^a, thus restoring the set of contacts 45 37 55 32 42, which have been under consideration, to their normal positions and wheel 4 will have arrived at the home point, thus causing rocker-arm 66 to move off projection 23^a.

The foregoing show how the first station on the system may be selected and called and the circuits restored; but if it had been desired to reach a station beyond the first station A on the system the drums 70 would have been operated to connect the sections 17^x 17^y of line 17^a through the station A and throughout the stations that intervene between station A and the station to be called. For instance, let it be supposed that the subscriber at station B desires to call the subscriber at station D, (station No. 4 on the system.) The calling subscriber first places his plug 13 in the aperture 11, corresponding to station D, which would be at aperture numbered 4 in ring 12. (See Fig. 4.) He then turns his handle 4^c until his switch 9 strikes plug 13, throwing 9 into engagement with 10 and breaking engagement of switch 20 with 21, four teeth on wheel 4 having passed into position under their rocker-arm 65. It will be understood that these rocker-arms cause no circuit to be completed until the plug has been reached and switches 9 and 20 have their positions changed thereby. Wheel 4 now starts to move toward the home point, and the first tooth 4^x thereof closes the selecting-circuit at 16 16^a by means of the rocker-arm 65, whereupon an impulse will be sent to ground 30 through contacts 31

32 31^a in the first station on the system A to cause the local circuit controlled by magnet 34 to close through the magnet 39, whereupon the corresponding drum 70 will be moved to change the positions of the contacts thereon relatively to their respective contacts connected with their various circuits. This tooth 4^x will next release rocker-arm 65, whereupon the circuit at 16 16^a will be broken to allow spring 79 to move the corresponding drum 70 another step, as before explained, whereupon contact 32 will be moved out of engagement with contacts 31 31^a, thus breaking magnet 34 and ground from the operating-circuit, and contact 37 will be drawn into engagement with contacts 35 36, whereby two sections of line 17^a will be connected together in the station under consideration, contact 45 will be moved away from contacts 44 46, contact 55 will be moved into engagement with contacts 54 56, and contacts 32 42 will be wholly out of engagement with their respective contacts 31 31^a and 41 43. The next tooth 4^x on wheel 4 will engage rocker-arm 65, thus sending another impulse from the selecting-circuit to ground 30 at the second station on the system B, performing the same operations on drum 70 thereat, principally to connect the two sections of line 17^a at 35 36 37. The following tooth 4^x on wheel 4 will cause the same operations to occur in the third station on the system C, likewise connecting two sections of line 17^a together thereat, a through-line to ground 30 at the fourth station on the system thus being established through the three stations A B C. The wide tooth 4^y at the calling-station will now arrive in engagement with rocker-arm 65, thus sending a long impulse direct to ground 30 through magnet 34 at the selected station, while at about the same time projection 23^a will engage rocker-arm 66 to close the calling-circuit at 15 15^a. The first effect of the impulse sent through the selecting-circuit so established by the influence of long tooth 4^y is to cause magnet 39 (through the closing of its local circuit at 34^a 38) to cause drum 70 at the selected station to move contact 45 into engagement with contacts 44 46 and to break the restoring-circuit in the selected station at 42 41 43, whereupon an impulse to produce a call in a selected station will be sent from the calling-station B through line 17 to portion 17^d, thence through 17^s (at the selected station) to 44^a, 44, 45, 46, 47, and through magnet 49 to ground 48. Magnet 49 thereupon closes the local circuit for the signaling instrument 50 at 49^a 51, and the continued movement of projection 23 and tooth 4^y now causes rocker-arm 66 to move from projection 23 into space 23^b, thus breaking the call-producing circuit, and immediately thereafter rocker-arm 65 moves from tooth 4^y, thereby breaking the selecting-circuit, whereupon spring 79 will move lever 78 so as to give drum 70 in the selected station the proper forward movement, during which time contacts 37 55 are

brought into engagement with their respective contacts 35 36 and 54 56, (contacts 32 and 45 having previously been moved out of engagement with their respective contacts in 5 the selected station, as before explained.) A continued movement of wheel 4 now causes projection 23^a to move rocker-arm 66 to close the corresponding circuit at 15 15^a, whereupon the restoring-circuit will be established 10 and will act as follows: from grounds 2 and 2^a through batteries 3 and 3^a and line 1 to the selecting-station B, thence to conductor 7 thereat, thence through contacts 6 and 5, conductor 8, switch 9, contact 10, wheel 4, frame 15 4^b, conductor 14, contact 15 to 15^a, conductor 15^b to line 17, thence along line 17 to station C through conductor 18^a thereat, thence through 6^b, 5^b, 21^a, 21, 20, 19, 5^a, 6^a and conductor 18 to line 17, thence to through the corresponding parts in station D to part 17^d of the line, thence through portion 17^s thereof (at D) to 53, 54, 55, 56, 57, and 33 through 34 to ground. The local circuit of magnet 39 is now closed, whereupon said magnet moves 20 drum 70 a proper distance, disconnecting contact 37 from contacts 35 36 and thereafter disconnecting contact 55 from contacts 54 56, thus deenergizing magnet 39, allowing spring 79 to move drum 70 to bring the corresponding contacts carried thereby to their home points, thereupon bringing contact 42 into engagement with contacts 41 43, thus reestablishing the circuit through line 17^d in the selected station. Projection 23^a still being 25 in engagement with rocker-arm 66 causes the current to continue to flow along line 17^d to station C, performing the same operations thereat just described with relation to station D, and so on through all the stations in which 30 instruments have been operated in selecting-station D, whereby all the circuits in all the stations that have been operated will be restored to their normal positions. Projection 23^a will now move from rocker-arm 66 to dis- 35 engage contacts 15 15^a, and all the parts throughout the system will be in their normal positions.

From the foregoing explanations it will be understood that the drums at 70 are always 40 moved forwardly in one direction, and as there are a number of sets of contacts 45 37 55 32 42 thereon one of these sets is utilized in each station that is operated in reaching the desired subscriber, the next set being 50 utilized the next time a subscriber is desired, and so continuously. Furthermore, it will be understood that the drum 70 is given four steps each equal to half the length of a tooth 73^a—that is to say, the first step is effected by the 55 current in magnet 39, which closes the calling-circuit at 45 and breaks the restoring-circuit at 42. The next step is caused by spring 79, which breaks the calling-circuit so established and closes the circuit through 37 and 55 and breaks the circuit through 32. The next step is caused by magnet 39, which breaks the circuit through 37 55, and the next

step is caused by spring 79, which restores the circuit through 32 42, leaving the drum in its normal condition. 70

Having explained how one subscriber may select and call another and then return the operated parts to zero, it remains to be described how the calling and called subscribers can be placed in telephonic communication. 75 One of the principal features of the invention is that a large number of subscribers can be accommodated on a comparatively small number of line wires or conductors, and another feature is that their telephone instruments 80 may be connected in closed metallic circuits. For these purposes I provide a number of main conductors or wires 80 80^a 81 81^a 82 82^a, and these conductors are used in pairs, as 80 and 80^a, 81 and 81^a, 82 and 82^a. There are a 85 considerably less number of pairs of such wires than there are stations on a system—for instance, a number of pairs of wires about equivalent to the greatest number of subscribers that would be telephoning at one 90 time—say five pairs of such wires for one hundred subscribers. I have shown in Figs. 1 and 1^a three pairs of wires for the telephone-circuit and four stations, this small number of stations being for convenience of illustration. 95 In each station on the system each conductor 80 80^a 81 81^a 82 82^a is connected with a contact, which contacts are separated or insulated from each other. In each station are contacts 83 84 85 83^a 84^a 85^a, one for each of 100 the telephone-conductors. The contact 83 is shown connected with main wire 80 by a conductor *d*, 83^a with main wire 80^a by a conductor *e*, 84 with main wire 81 by a conductor *f*, 84^a with main wire 81^a by a conductor 105 *g*, 85 with main wire 82 by a conductor *h*, and 85^a with main wire 82^a by a conductor *i*, the same arrangement being made in each station, and so on in each station for as many pairs of such telephone-conductors as there 110 are on the system. Thus when contacts 83 83^a are electrically connected through the device the circuit will be from 80, through *d*, 83, to 83^a and *e*, to 80^a, and similarly for the other corresponding conductors and contacts. 115

86 is a contact or metal plate placed near and parallel to contacts 83^a 84^a 85^a, but insulated or separated therefrom.

A cylinder or drum 124 is provided carrying suitable plates or contacts. The drum 120 has two movements—namely, a rotary movement, effected by spring-actuated mechanism, and a longitudinal movement—i. e., a movement to the right caused by the armature 123 of magnet 122 and to the left by means 125 caused to operate by the hanging of the receiving-telephone on its hook, the same action reversing the rotary motion and returning all parts to normal position, as herein-after specifically explained. The plates or 130 contacts carried by the drum are adapted to be engaged by suitable spring-contacts. In the normal position of the drum 124, as shown in Fig. 1, at station A a long contact 114 is

in engagement with spring-contacts 113 and 115, a broad contact 132 is in engagement with spring-contacts 131 and 133, a contact 88^a is in engagement with spring-contacts 119 5 and 88, a contact 104 is out of engagement with contacts 103, 105, and 106, and a contact 138 is out of engagement with 137 and 139. Movable with the drum 124, but adapted to be arrested in its progress, is an arm 94, 10 carrying and in electrical engagement with a contact 95, adapted to engage contacts 83 84 85, &c., and insulated contacts 96 and 97 in electrical connection with each other, contact 96 being adapted to engage contacts 83^a 15 84^a 85^a, &c., and the contact 97 being adapted to engage contact 86. Fixed on the arm 94 and moving with it is a toothed wheel 98. A magnet 101 has an armature 100, provided with a detent-point 99, adapted to engage 20 teeth 98^a on said wheel and to arrest the progress of the arm. The arrangement is such that when arm 94 is stopped by said detent the drum 124 is not arrested, but moves to its destined position. When a subscriber re- 25 moves his receiver 91 from its hook 144, arm 94 moves over the contacts 83^a 84^a 85^a, &c., and the drum 124 rotates. This rotation brings plate or contact 104 in engagement with contacts 103 and 105. When the drum 30 has reached its final position, plate or contact 138 will be in engagement with spring-contacts 137 and 139, and plate or contact 104 will then be out of engagement with 103 and 105, part 88^b of plate or contact 88^a will be in 35 engagement with spring-contact 88 only, contact-plate 132 will be out of engagement with spring-contacts 131 and 133, and plate 114 will be still in engagement with 113 and 115. If now drum 124 be thrown to the right (in the 40 drawings) by the action of armature 123 of magnet 122, the relations of the contacts on the drum and the spring-contacts will be as follows: 138 will engage 137 only, 104 will be out of engagement with 103 and 105, part 88^b 45 of 88^a will be in engagement with contacts 88 and 89, contact 132 will still be out of engagement with its spring-contacts, contact 114 will engage contacts 115 and 135. (This is the normal position of drum 124 and its 50 contacts when circuits are completed for conversation.) Drum 124 is also adapted to be moved to the right by armature 123 of magnet 122 before the receiver is removed from its hook and the drum rotated, in which case 55 the relative positions of contacts on the drum and the spring-contacts will be as follows: Contact 88^a will be in engagement with 88 only, contact 132 will be in engagement with 131 and 133, and 114 will be in engagement 60 with 115 and 135. Now when drum 124 is rotated these same positions will be preserved, contact 104 moving into engagement with contact-springs 103 and 106. When the drum has rotated its full distance, the positions 65 will be the same as described above for the purpose of conversation. From contact 86 extends a conductor 87, that leads to contact

88. Contact 89 is connected by a wire 90 with one side of telephone-receiver 91. From the other side of this receiver extends a conductor 92, that includes the secondary of an induction-coil 93 and leads to the arm 94. 70

One of the purposes of my invention is to enable contacts 95 96 97 in each station to select an idle or unemployed pair of main 75 conductors automatically, and in connection therewith I have arranged the system so that after the appropriate parts in a calling-subscriber's station have selected a pair of idle main conductors the corresponding parts in 80 a called station will act to select the same pair of wires to place the telephone instruments in a calling and a called station in a closed metallic circuit over said selected conductors. Magnet 101 is located on a normally 85 open local circuit organized as follows: From one terminal of magnet 101 extends a conductor 102, that leads to the contact 103, which is normally out of engagement with but adapted to be engaged by the contact 104. 90 The contact 104 in the calling - station is adapted to engage the contact 105, while in the called station contact 104 is adapted to engage contact 106, as hereinafter explained. The contact 105 is connected with a conductor 95 107, that leads to a contact 108, which is normally engaged by an armature 109, (or a contact operated thereby.) The armature 109 (or the contact operated thereby) is connected by a conductor 110, that leads to conductor 27 100 on one side of battery 28. From conductor 27, on the other side of battery 28, a conductor 111 leads to the terminal of magnet 101 opposite to conductor 102. Magnet 122 is operated in two ways. In one case when magnet 49 is 105 operated in a called station to ring the corresponding bell the current from the battery 28 passes not only through the bell 50, but also through magnet 122, as follows: From one 110 side of magnet 122 a conductor 127 leads to wire 111, the circuit leading thence to wire 27 and to one side of battery 28, thence from other side of battery 28 over wires 40^a 52^a, armature 49^a, contact 51, wires 52 and 126, to wire 125, and back to magnet 122. A circuit 115 for magnet 122 is also formed when drum 124 has been rotated before being moved lengthwise, as follows: from one side of magnet 122, to wire 125, to spring-contact 139, thence by plate 138, (as drum has been rotated,) to 120 spring-contact 137, wire 128, contact 129, (adapted to be engaged by armature 109 of magnet 117,) through armature 109, wire 110, wire 27, through battery 28, to wire 111, thence by wire 127, back to magnet 122. When a 125 calling-station's arm 94 automatically seeks an unemployed circuit in order to secure it for itself, it seeks for a pair of wires which are open throughout—that is, where no connection has been formed between the wires 130 of such a pair through the telephones of other stations that may be using those wires. Therefore any calling-station's arm 94 seeking for a pair of wires not connected together would

pass over the contacts corresponding to the busy wires, as 81 81^a, without being arrested. The circuits which enable this passing of the arm 94 are as follows: Suppose an attendant 5 at any station, as A, desires to communicate with some station, as C. Having called station C over the calling-circuit in the manner previously described, he removes his receiving-telephone from its hook on arm 144. 10 This starts the rotation of his drum 124 and also starts the movement of arm 94. We will now suppose that wires 80 and 80^a are in use, and therefore connected together through some user's telephone, as previously described. 15 When, therefore, arm 94 reaches the contacts 83 and 83^a, representing wires 80 and 80^a, a circuit is instantly formed as follows: from grounds 2 and 2^a, through batteries 3 3^a, over wire 1, to wire 112, thence to spring-contact 20 113, contacts 114 115, wire 116, to magnet 117, thence by wire 118, over wire 92, arm 94, contact 95, contact 83, wire d, to main wire 80, (all at the calling-station,) over 80 and through the telephones of subscribers using 25 the wires to wire 80^a, back over wire 80^a, to wire e, contact 83^a, contacts 96 97 86, wire 87, to spring-contact 88, contact 88^a, spring-contact 119, thence by wire 120, to ground 121. This circuit being thus closed through 30 magnet 117 causes it to attract its armature 109. This breaks the local circuit of magnet 101, as before described, at 109 108. Magnet 101 cannot therefore attract its armature 100, and thereby arrest arm 94. The arm 35 94 will therefore pass on to the next pair of contacts 84 84^a, and as the wires connected to these contacts are also busy the circuit for 117 will still be unbroken (as contacts 95 and 96 are arranged (see Fig. 9) to make contact 40 with the next pair of contacts before breaking from the one they are on, thus contact 95 engages 84 just before breaking from 83 and 96 engages 84^a just before breaking from 83^a) and arm 94, continuing its movement, passes on to contacts 85 and 85^a. If 45 the wires connected with these latter contacts are not in use, there will be no connection between 82 and 82^a, so that when arm 94 passes on to these contacts the circuit through magnet 117 will in consequence be broken. Magnet 117 thereupon releases its armature 109, causing the local circuit through magnet 101 to be closed at 109 and 108, as follows: from armature 109, over wire 110, wire 27, including battery 28, wire 111, magnet 101, wire 102, contacts 103 104 105, wire 107, and contact 108, back to armature 109. Magnet 101 thereupon attracts its armature 100, causing 50 detent 99 to be thrown into engagement with a tooth 98^a of wheel 98, thus stopping the progress of arm 94 over contacts 85 85^a, which represent connection to the first pair of idle wires, and drum 124 continues its rotation to its destination. It will be noticed that battery 55 from wire 1 is left on the selected line 82 through magnet 117, also that the ground 121 is removed from wire 82^a. The position of

the circuit showing this is as follows: from battery-line 1 to wire 112, contacts 113 114 (as 114 is still in connection with 113 and 115) 70 wire 115, wire 116, magnet 117, wire 118, by wire 92, to arm 94, contact 95, contact 85, wire h, to wire 82. The ground 121 is broken from 82^a as follows: from 82^a to wire i, contact 85^a, contacts 96 97 86, and wire 87, to contact 88, and 75 as contact 119 is not connected through part 88^a of contact 88^a to contact 88 the circuit over wire 120 to ground 121 is therefore broken between 88 and 119.

Having explained the manner in which the 80 arm 94 at the calling-station selects and makes connection with a pair of idle wires, I will now explain the manner in which the arm 94 at the called station makes connection with the particular wires selected by the calling-station. It must be remembered that the calling-station has left a battery from wire 1 upon line 82. Now in the called station when the bell or signaling instrument was operated the local circuit of magnet 122 was completed 90 in manner already described through the action of armature 49^a of magnet 49 energizing magnet 122. The drum 124 was moved to the right, and a circuit was formed for magnet 117 in the called station when the receiver 95 was removed from the hook, as follows: The removing of receiver 91 from its hook permitted the drum to rotate, and arm 94 moved over the contacts 83 83^a 84 84^a, &c. Arm 94 cannot stop until it makes such connections as will 100 complete the circuit through magnet 117 to ground 121 for the battery-current put on wire 82 at the calling-station. The called station cannot now select an idle pair of wires, as the contact 114 has moved from under 113, thus 105 cutting off battery connection through 112 to line 1 at that station. The contact 104 is now under 103 106, (the moment the drum begins to revolve,) and contact 119 is out of engagement with 88^a. The circuit from the 110 charged line 82 will now extend as follows: from wire h, to contact 85, contact 95, (when arm 94 has reached said contact,) arm 94, wire 92, wire 118, magnet 117, wire 116, contacts 115 114, (as 114 is out of engagement 115 with 113 and in engagement with 115 and 135,) contact 135, wire 134, to contact 133, contact 132, contact 131, and wire 130, to ground 121. This completes the circuit of the battery put on to wire 82 at the calling-station through 120 magnets 117 in both the stations. In the called station magnet 117 attracts its armature 109 and completes the local circuit through magnet 101 at 109 and 129, the local circuit being as follows: from armature 109, 125 to wire 110, wire 27, through battery 28, wire 111, magnet 101, wire 102, to contact 103, (contact 104 being now under 103 106,) contact 104, 106, wire 128, and contact 129 to armature 109. Magnet 101 thereupon attracts its 130 armature 100, causing detent 99 to engage a tooth 98^a of wheel 98, thus arresting the progress of arm 94 over contacts 85 85^a, securing connection to the wires desired, (82 82^a). In

the calling-station magnet 117 also attracts its armature 109, completing the local circuit for magnet 122 in that station as follows: armature 109, wire 110, wire 27, through battery 28, wire 111, wire 127, magnet 122, wire 125, spring-contact 139, (drum 124 having rotated its full distance and brought contact 138 under contacts 137 and 139,) contact 138, contact 137, wire 136, to wire 128, and by contact 129 back to armature 109. Magnet 122 (at the calling-station) thereupon attracts its armature 123, moving drum 124 at that station to the right and breaking the local circuit of magnet 122 at 139 138. The battery-circuit leading from wire 1 is now broken as follows: from wire 1, to wire 112, and contact 113; and as contact 114 has been moved away from contact 113 and is now under 115 135, said battery-circuit will be broken at 113 114. Part 88^b of contact 88^a now completes connection between 88 and 89.

For the purpose of illustrating the circuit just described I have shown in the drawings Figs. 1, 1^a the stations B and D as in connection for conversation. We must suppose station B to have called station D and that all necessary movements and connections have been made as described. The positions of the different parts and the connections formed will be as follows: The arm 94 at both stations has been arrested on the first pair of idle wires at the time of the call—say 81 and 81^a, (supposing wires 80 and 80^a to be already engaged by other stations,) represented by contacts 84 and 84^a. From contact 84 in station B the circuit extends over wire 81 to contact 84 in station D, thence by contact 95 on arm 94 at D over arm 94 and wire 92, through the secondary of induction-coil 93 to receiving-telephone 91, thence by wire 90 to contact 89, part 88^b of contact 88^a, contact 88, wire 87, contact 86 to insulated contact 97, thence to 96 84^a over wire g to wire 81^a, over the latter to wire g in station B, thence to contacts 84^a 96 97 86 87 88 88^b 89, wire 90, receiving-telephone 91, wire 92, through secondary of induction-coil 93, arm 94, and contact 95 back to contact 84 in station B. Receiver 91 having been removed from the hook of arm 144 at both stations, arms 144 will have engaged contacts 140 and have thus completed the local circuits through transmitters as follows: From transmitter 142 extends a conductor 143, which leads to the primary of induction-coil 93 over conductor 143^a, conductor 27, to one side of battery 28, conductor 27, from other side of battery 28, wire 111 111^a, arm 144, contact 140, and wire 141, back to transmitter 142. This circuit is the same at both stations. The arrangement of the parts is such that when receiver 91 is hung upon hook 144 arm 94 will be moved clear of contacts 83 83^a, &c., as in stations A and C, and drum 124 will be moved back to zero.

The mechanism I have devised for causing the various and independent movements of

arm 94 and drum 124 is clearly illustrated in Figs. 2, 3, 9, 10, 11, 12 and is as follows: The drum of cylinder 124 is loosely mounted on a shaft 145, so it can slide thereon, and the shaft 145 is journaled in suitable bearings in a frame 146. The drum 124 has an aperture to receive a pin 147, so that it can freely slide lengthwise of said pin and shaft 145, and said pin is carried by an arm or disk 147^a, secured to shaft 145 and which serves as an abutment for drum 124 to stop the latter in the proper place when it is moved by magnet 122. Pin 147 causes drum 124 to turn with shaft 145. The armature 123 of magnet 122 is connected with an arm 123^a, that acts to push drum 124. (See Fig. 11.) As shown clearly in Figs. 9, 10, and 11, arm 123^a is carried by a rock-shaft 123^b, journaled in bearings 85 on frame 146, and armature 123 is carried by arm 123^a. (See Fig. 11.) Drum 124 is moved back to the normal position by a pin 148, carried by drum 124, acting against a spring-arm 149, which has a curved part 149^a (see Fig. 3) so arranged as to allow pin 148 to travel with drum 124 along shaft 145 (by the action of arm 123^a) and to move forwardly or over with said drum; but when the drum is turned back on its axis the curve of said spring 149 will act on said pin to move the drum back along shaft 145 to the normal position. The arm 94 is loosely hung on shaft 145, and the toothed wheel or disk 98 is also loose on said shaft, but rigidly connected with said arm. (See Fig. 11.) The shaft 145 carries a pin 150, shown attached to an arm 150^a, secured to said shaft, the pin 150 normally lying beneath arm 94 and being adapted to encounter and raise said arm and to support the latter in its normal home position. (See Figs. 9 and 11.) The shaft 145 is to be rotated through the medium of arm 144, and to enable said shaft to be given a maximum motion with a minimum movement of arm 144 I have shown said shaft and said arm connected by suitable gearing. Furthermore, in order to move arm 94 to enable it to select the proper pair of main telephone-conductors and to cause arm 144 to close the local circuit for the transmitter 142 I have provided a spring 151 to operate the before-mentioned gearing. (See Fig. 11.) Said gearing is arranged as follows: Arm 144 is secured to a shaft 152, that is journaled in frame 146, and said shaft carries a gear-wheel 153, that meshes with a pinion 154, carried by an arbor 154^a, journaled in frame 146. Pinion 154 meshes with a pinion or gear 155, secured on shaft 145. (See Figs. 9, 10, 11.) To the pinion or gear 155 is secured an arm 156, which normally rests beneath a pin 157, that is attached to a ratchet-wheel 158, loosely mounted on shaft 145. Ratchet-wheel 158 is in engagement with a spring-acting pawl 159, that is carried by a gear-wheel 160, loosely mounted on shaft 145. Spring 151 is connected with frame 146 and is also connected with wheel 160, being shown so connected through the

medium of a disk 161, having a sleeve 162, to which the inner end of spring 151 is connected. To retard the influence of spring 151, I have shown wheel 160 in mesh with a pinion 163, 5 that is connected with a gear-wheel 164, which in turn meshes with a pinion 165, connected with a gear-wheel 166, that meshes with a pinion 167, the pinion 167 being connected with a fan 168. The parts 163, 164, 165, 166, 10 167, and 168 are supported by suitable shafts journaled in frame 146. In Figs. 2, 9, and 10 contact 140 of the local transmitter-circuit is shown carried by frame 146, while arm 144 acts upon a contact 144^a, also carried by said 15 frame, through the medium of a projection 144^b, carried by said arm. Contact 144^a is connected with conductor 126. Between arms 94 and 150^a is located a friction device 169, shown in the form of a spiral spring coiled 20 around shaft 145 and pressing simultaneously against arms 94 and 150^a, so that the latter will move the former uniformly and will yet allow arm 94 to come to rest when stopped by detent 99 and a tooth 98^a, so 25 that arm 150^a can continue its movement. The coaction of the foregoing parts is as follows: When receiver 91 is hung upon hook or arm 144, its weight carries down said hook or arm, thus breaking the local transmitter-circuit at 140 144^a, whereupon wheel 30 153 communicates motion to gear 155 and shaft 145, whereupon arm 156 acts, through pin 157, wheel 158, pawl 159, gear 160, and disk 161, to wind up spring 151, while at the same time 35 pin 150 moves arm 94 to its normal position. (See Figs. 2 and 9.) The shaft 145 likewise turns drum 124 back to its home point. Now when the receiver 91 is removed from hook or arm 144 the spring 151 acts to turn shaft 145 40 in the direction of the arrow S in Fig. 9 through the medium of parts 162, 161, 160, 159, 158, 157, and 156, whereupon gear 155, through the medium of gear 153 and shaft 152, raises arm 144. As shaft 145 thus turns 45 arm 150^a pin 150 follows (drum 124 likewise being turned from the home point) and allows arm 94 to descend to enable its contacts 95 96 97 to pass over contacts 83 83^a 86, &c., until contacts 95 96 select a pair of idle main 50 telephone-conductors, whereupon detent 99 engages a tooth 98^a to hold contacts 95 96 in engagement with a pair of contacts 83 83^a or 84 84^a or 85 85^a corresponding to the main telephone-conductors so selected; but shaft 55 145 continues its movement, carrying drum 124 with it and continues to raise arm 144 until its projection 144^b presses contact 144^a into engagement with contact 140 to close the local transmitter-circuit and to also stop the 60 movements of the parts. When receiver 91 is next hung upon hook or arm 144, spring 151 will be again wound, and pin 150 will again raise arm 94 to its normal position, as before set forth.

65 The complete operation in detail of all the circuits and devices hereinbefore described whereby one subscriber may select and call

another and may select a pair of idle main telephone-conductors and whereby the called subscriber may select the same pair of main 70 telephone-conductors may be described as follows: Suppose a subscriber at station B, Fig. 1, desires to communicate with a subscriber at station D, Fig. 1^a. The operator at station B places his plug 13 in the aperture 11, which corresponds to the station to be called, as aperture 11, numbered 4 in Fig. 4. He then turns his handle 4^c until his switch 9 strikes plug 13, which moves said switch into engagement with contact 10 and moves switch 20 out 80 of engagement with contact 21, thereby establishing the selecting-circuit in the calling-station at 910 and breaking the normal circuit through line 17 in the calling-station at 20 21. When wheel 4 was thus moved by handle 4^c, 85 the presser 25 moved away from contact 24^c, thus breaking the shunt around magnet 24, and tooth 4^y and three teeth 4^x passed under rocker-arm 65, no electrical connection, however, being formed, while projections 23 23^a 90 were moved under rocker-arm 66. When the operator releases handle 4^c, the corresponding spring 60 will move wheel 4 back toward its home point, whereupon the first tooth 4^x will move rocker-arm 65 to close the selecting-circuit at 16 16^a, whereupon the circuit 95 will be closed through the subscriber-selecting instruments in the first station on the system A as follows: from grounds 2 2^a and batteries 3 and 3^a to line 1, and thence to conductor 7, station B, thence through 6 5 8 9 10, wheel 4, frame 4^b, conductor 14, contact 16, contact 16^a, and conductor 16^b to line 17, thence along said line to the first station on the system A and through 17^a thereat to 31 32 31^a 33, 100 magnet 34, and ground 30. Magnet 34 at A now attracts its armature 34^a, which closes the local circuit for magnet 39 as follows: from 38, through 38^a 39 40 27 and battery 28, to 40^a, thence back to 34^a. Magnet 39 thereupon attracts its armature 39^a, which through 105 the medium of pawl 74^b, Fig. 8, moves the corresponding drum 70 one step forward. This movement disconnects contact 42 from 41 43 and moves contacts 32, 55, 37, and 45 forwardly, at that time bringing contact 45 into engagement with contacts 44 46, thereby establishing a circuit to cause the operation of signaling instrument 50; but as station A is not the station desired wheel 4 continues to 110 move, thereby carrying corresponding tooth 4^x away from rocker-arm 65, thus breaking the selecting-circuit at 16 16^a, whereupon armature 34^a moves back and magnet 39 becomes deenergized. Spring 79 at A now 115 draws lever 78, which causes pawl 75^b to turn drum 70 at A another step forward, whereupon contact 45 is moved away from 44 46, thus breaking the previously-formed bell-circuit, moving contact 37 into engagement with 120 contacts 35 36, thereby joining two sections of line 17^a, as 17^x 17^y, together at station A, through to ground 30 at station B. Drum 70 likewise connects 55 with 54 56 to form the 125 130

restoring-circuit and moves contact 32 out of engagement with contacts 31 31^a. The next tooth 4^x on wheel 4 engages rocker-arm 65 to again close the selecting-circuit at 16 16^a, 5 whereupon an impulse will be sent over the circuit first described and through station A at 35 37 36 to ground 30 at station B. Drum 70 at station B will now be operated by the action of magnet 39 and spring 79 to make and break the similar circuits at B, as first described with relation to the drum 70 at station A, thus establishing a circuit through station B at 35 36 37 to ground 30 at station C. Tooth 4^x moves from rocker-arm 65 to again break the circuit at 16 16^a to enable spring 79 to complete the breaking and making of circuits at station B. The next tooth 4^x operates rocker-arm 65 again to close the circuit at 16 16^a with an effect in station 20 C similar to that described with relation to stations A and B, thereby establishing a circuit to ground 30 at station D through 35, 36, and 37 at station C. The tooth 4^y and the projection 23 now respectively engage rocker-arms 65 66 at the calling-station, whereupon rocker-arm 65 by closing the circuit at 16 16^a will cause magnet 39 at station D to so move drum 70 thereat as to bring contact 45 into engagement with contacts 44 46, and as tooth 25 4^y is comparatively long magnet 39 will be kept energized to hold contacts 44 45 46 together, during which time projection 23 will cause rocker-arm 66 to close circuit at 15 15^a to produce a signal in station D as follows: 30 from grounds 2 2^a and batteries 3 and 3^a and line 1 to the calling-station B, thence through conductor 7, contacts 6 5 8 9 10, wheel 4, frame 4^b, conductor 14, contact 15 to 15^a 15^b to line 17, thence along line 17 to the right in 35 Fig. 1^a to portion 17^d thereof, thence through 17^s to 44^a 44 45 46 47 and magnet 49 to ground 48 at the selected station. (Had any station on the system intervened from the right between the calling and the selected station the 40 circuit would have led through contacts 41 42 43 at such intervening station.) Magnet 49 at station D now attracts its armature 49^a to close the local circuit for signaling instrument 50 at D from 51, through 52 and 50 to 45 5^a 27, through battery 28 to 40^a, thence to 52^a and 49^a, back to 51. The signaling instrument 50 will thereupon operate to produce a call, and current from battery 28 will divide and act to push drum 124 in the called station 55 along its shaft 145 through the circuit now established as follows: from 51 to 126^a 126 125, to magnet 122 at D, thence through 127 to 111, to 27, back to 51, whereupon magnet 122 acts, through its armature 123 and 60 arm 123^a, to push the corresponding drum 124 along its shaft 145 into the position shown at station D in Fig. 1^a; (but this drum 124 has not yet been rotated.) Projection 23 next passes from rocker-arm 66; thus breaking the 65 call-producing circuit at 15 15^a, whereupon rocker-arm 65 next moves from tooth 4^y, again breaking the selecting-circuit at 16 16^a, and spring 79 in the called station D next draws lever 78 to give drum 70 another step forward, whereupon said drum acts to bring 70 contact 55 into engagement with contacts 54 56 and contact 37 into engagement with contacts 35 36. The continued movement of wheel 4 next brings projection 23^a under rocker-arm 66, thereby causing the latter to 75 again close circuit at 15 15^a, whereupon an impulse will be sent through the line 17 17^d, &c., to restore all the selecting instruments that have been operated to their normal conditions, as follows: from 2 2^a through batteries 3 and 3^a and line 1 to conductor 7, (at the calling-station B,) to contacts 6 5 8 9 10, wheel 4, frame 4^b, conductor 14, contacts 15 15^a, and conductor 15^b to line 17, thence through line 17 to the right (in Fig. 1^a) to portion 17^d thereof, thence through 17^s to 54, 55, 56, 57, 33, and magnet 34 to ground 30. Magnet 34 attracts its armature 34^a, again closing the selecting-circuit for magnet 39 at the called station, which latter attracts its armature 39^a, where- 80 by lever 78 and pawl 74^b will move the corresponding drum 70 forward one step, thereupon moving contact 37 from contacts 35 36, and immediately thereafter moving contact 55 from 54 56, thereby breaking the circuit 85 thus described, deenergizing magnet 34, opening the local circuit of magnet 39, and allowing spring 79 (at D) to draw lever 78, causing pawl 75^b to push drum 70 forward to its normal position, thus closing the restoring-circuit 90 at 41 42 43, (likewise bringing contact 32 into engagement with 31 31^a,) whereupon (projection 23^a still acting on rocker-arm 66) the current will travel from D through 17^s, 41, 42, 43, and 17^t to 17^d, thence to station C 95 through 17^s to 53, 54, 55, 56, 57, 33, and magnet 34 to ground 30, thereby performing the same operation at C of moving drum 70 forward to break circuit at 54 55 56 and to close circuit at 41 42 43, whereupon the current will like- 100 wise travel to station B, performing the same operations thereat of moving drum 70 forward to break the ground-circuit at 30 and establish the through-circuit at 41 42 43, similar operations taking place at station A, (the 105 last station on the circuit,) thereby moving the drum 70 forward with a similar effect. Springs 79 between the called station and the last station on the circuit likewise finally move their respective drums 70 to the normal positions, whereby all the selecting instruments that have been operated in selecting a station are returned to their normal positions. Thereupon projection 23^a will pass from rocker-arm 66, causing contacts 15 15^a 110 to separate, and when wheel 4 reaches the home point its presser 25 will act to close the shunt around magnet 24 at 24^b 24^c. Should any other subscriber during the time that the subscriber at station B was operating have 115 attempted to move his wheel 4 to select a subscriber, the first action would have been to open the shunt around his magnet 24 at 24^b 24^c by the movement of his presser 25 away 120 125 130 135

from said contacts. The line being then charged through the action of the wheel 4 in the calling-subscriber's circuit closing the normal circuit through line 1, magnet 24 at 5 the interfering-subscriber's station would have attracted its armature 24^f to close the local circuit through his magnet 26, as follows: from 27^a through 27 and battery 28 to magnet 26, thence through conductor 27^b and 10 armature 24^f (or a contact operated thereby) back to 27^a. Thereupon magnet 26 would have attracted its armature 26^a to move detent 26^b into the path of the tooth 4^x of the interfering-subscriber's wheel 4, thus blocking 15 the movement of said wheel; but as soon as the calling-subscriber's wheel 4 returns to the home point the line will be cleared for another subscriber's use. The calling subscriber next removes his receiver 91 from 20 hook or arm 144, whereupon spring 151 causes shaft 145 to turn in the direction of arrow S in Fig. 9, thus allowing arm 144 to rise, causing drum 124 to turn forwardly, also allowing arm 94 to descend, drum 124 first 25 causing contact 104 to engage contacts 103 and 105. Contacts 95 96 97 now pass over contacts 83 83^a 86, &c., and if the first pair of main telephone-conductors 80 80^a are employed arm 94 will continue to move, because 30 a circuit will be established through magnet 117 in the calling-station to break the local circuit established by contacts 103 104 105, as follows: from grounds 2 and 2^a and batteries 3 and 3^a and line 1 to 112, 113, 114, 115, 35 116, magnet 117, wire 118, 92, 94, 95, 83, and d to 80, (all in the calling-station,) thence along line 80 to d in the station using the line, through d to 83, 95, 94, 92, 93, 91, 90, 89, 88^b, 88, 87, 86, 97, 96, 83^a, e, and 80^a, back over 40 line 80^a to wire e, (at the calling-station,) 83^a, 96, 97, 86, 87, 88, 88^a, 119, 120, to ground 121. Magnet 117 in the calling-station will thereupon attract its armature 109 and keep the local circuit of magnet 101 broken, whereupon 45 arm 94 in the calling-station will continue to move until it finds a pair of idle or unemployed main telephone-conductors, whereupon the circuit of magnet 117 will be opened and arm 94 will be brought to rest by 50 the action of magnet 101, because no other circuit can then be established for magnet 117. Thereupon magnet 101 will be energized by its circuit so established by drum 124 at 103, 104, and 105 and will attract its armature 100, thereby causing detent 99 to engage tooth 98^a of disk 98. The position of arm 94 at this time will be seen at station B (the calling-station) in Fig. 1, arm 94 being shown (at B) to have selected the pair of main telephone-conductors 81 81^a. Drum 124 at the calling-station will continue to move until it comes to rest, during which time it will bring contact 138 into engagement with contacts 137 139, will move contact 104 out of engagement with contacts 103 105, bringing the part 88^b of contact 88^a into a line parallel with the end of contact 89, and will move contact 132

out of engagement with contacts 131 133. The arm 144 causes contact 144^a to engage contact 140 in the calling-station, thus closing the local circuit for the transmitter 142 thereat. The called subscriber removes his receiver 91 from its hook or arm 144, whereupon the corresponding spring 151 causes his arm 144 to rise and his drum 124 to rotate forwardly, thus allowing his arm 94 to descend, (it being remembered that his drum 124 had been pushed along its shaft 145 by the corresponding magnet 122 when the call was received at his station.) When the corresponding contacts 95 96 (at the called station) pass over the contacts 83 83^a corresponding to these main line conductors which are in use by some other subscriber his arm 94 will not be arrested, because the called subscriber is searching for a wire with a battery-current on it and his arm will not stop until it reaches such wire, and at that time there is no circuit for magnet 101, (as contact 104 was previously pushed out of line with contacts 103 105,) and although contact 104 comes in engagement with contacts 103 106 there is no circuit for magnet 117 in the called station, as the circuit for such magnet in the called station is only established through a pair of main telephone-conductors that have been selected by the calling subscriber; but when contacts 95 96 of the called station reach the contacts connected with the main telephone-conductors 81 81^a which were selected by the calling subscriber a circuit will be established through magnet 117 at the called station from the battery connections of the calling-station, as follows, (arm 94 at the called station having now reached contacts 84 84^a corresponding to main conductors 81 81^a that were selected by the calling-station, as at station D in Fig. 1^a, it being remembered that drum 124 in the calling-station has not yet been pushed over by magnet 122 thereat, which is now controlled by the called station:) from ground 121 at the called station D, through 131, 132, 133, 134, 135, 114, 115, 116, magnet 117, 118, 92, 94, 95, 84, and f at the called station, to 81, along 81 to f at the calling-station, to 84, 95, 94, 92, 117, 116, 115, 114, 113, 112, to line 1, through the battery 3 or 3^a to ground 2 or 2^a, or both. Magnet 117 in the called station D now attracts its armature 109, which closes a circuit for magnet 101 through 102, 103, 104, 106, 128, 129, 109, 110, 27, battery 28, to 111, back to 101, whereupon magnet 101 attracts armature 100 and causes its detent 99 to engage the tooth 98^a of disk 98 to arrest the movement of arm 94 to keep its contacts 95 96 97 in connection with contacts 84, 84^a, and 86. Thus the contacts carried by arms 94 in the calling and the called station are both held in circuit with the same pair of main telephone-conductors 81 81^a. During the time that magnet 117 in the called station D was energized to arrest arm 94, as stated, magnet 117 in the calling-station was energized to form a circuit through magnet 122 to push the corresponding drum

124 over, to finally complete a closed metallic circuit between the receivers at the calling and the called stations, as follows: from 122, through 125, to 139, thence 138, (which at this time is in engagement with 137 139,) thence through 137, 136, 128, 129, 109, 110, 27, and battery 28 to 111, thence to 127, and back to magnet 122. Magnet 122 thereupon attracts its armature 123, which by means of arm 123^a moves the drum 124 (in the calling-station B) to the position shown at B in Fig. 1, thereby disconnecting 139 from 138 and moving 105 out of line with 104, moving 119 away from 88^a and 89 into line with 88^b, and also disconnecting 113 from 114, thus breaking off line-battery. The final forward movement of drum 124 in the called station D brings contact 89 into engagement with contact 88^b, and a complete closed metallic circuit through the receivers 91 in the calling and the called stations is thus automatically established, which may be traced as follows: starting from receiver 91 at station B through 92, including the secondary of induction-coil 93, to 94, thence to 95, 84, and f, to 81, thence along conductor 81 to f in the called station, thence through 84, 95, 94, 92, and the secondary of induction-coil 93 to receiver 91, thence through 90, 89, 88^b, 88, 87, 86, 97, 96, 84^a, and g to main telephone-conductor 81^a, thence along said conductor to g in the calling-station, thence through 84^a, 96, 97, 86, 87, 88, 88^b, 89, and 90 back to receiver 91 at the calling-station, (the starting-point.) Arm 144 at the called station will now have caused its projection 144^b to close the local circuit for its transmitter at 140 144^a. The calling and the called subscribers will now be in complete closed metallic telephonic communication. When they have finished talking, they each hang their receivers upon their respective hooks or arms 144, which descend, wind up springs 151, turn drums 124 back to their home positions, and raise the arms 94 to their normal positions, during which movement of each drum 124 the corresponding pin 148 which it carries will engage the curved part 149^a of spring 149, which will thereupon act to move the drum lengthwise on its shaft 145 and restore said drum to its normal home position.

In practice I mount all the operating devices, contacts, connections, &c., upon a suitable board or support E, and upon this board or support I secure a receptacle F, within which are placed batteries and magnets for relays and locals, and by preference I secure the signaling instruments 50 to the receptacle F, all as shown in Figs. 2 and 3, the line conductors or wires being connected with suitable binding-posts carried by support E, from which binding-posts suitable connections lead to the appropriate contacts, magnets, &c.; but of course the devices, contacts, &c., can be otherwise supported, if desired.

I do not limit my invention to the details of construction and arrangement shown and

described, as they may be varied without departing from the spirit of my invention.

Having now described my invention, what I claim is—

1. A signaling system comprising a circuit having a battery and a magnet, a local circuit adapted to be closed by said magnet, a local circuit including a battery and a signaling instrument, a normally open circuit having a magnet to be connected therewith to close the signaling-instrument circuit, and electrically-operating devices connected with the first-mentioned local circuit for closing said normally open circuit to enable the magnet on the latter circuit to close the signaling-instrument circuit.

2. A signaling system comprising a circuit leading to ground and including a magnet, a normally open local circuit having an armature to be operated by said magnet for closing said local circuit, a normally open circuit, a magnet and contacts to be connected therewith, electrically-operating devices connected with said local circuit and arranged to break the first-mentioned circuit and to close the third-mentioned circuit through said contacts, a normally open local circuit including a battery, a signaling instrument and an armature, the latter being arranged to be actuated by the magnet on the third-mentioned circuit to close the signaling-instrument circuit.

3. A signaling system comprising a plurality of stations, a circuit for said stations divided into sections in each station, each of said sections normally leading to ground and having a magnet, contacts to join the adjacent sections of said circuit together, a second circuit for said stations, a normally open branch therefrom in each station, means controlled by the first-mentioned circuit for closing the corresponding branch, and means in each station to produce a signal when current is thrown on said second-mentioned circuit.

4. A signaling system comprising a plurality of stations, a circuit for said stations divided into sections in each station, each of said sections normally leading to ground and having a magnet, contacts to join the adjacent sections of said circuit together, a normally open local circuit in each station having an armature to be operated by the corresponding magnet, another circuit passing through said stations and having a normally open branch line in each station leading to ground and including a magnet, contacts in each station to make and break said circuit, and contacts in each station to make and break said branch lines, electrically-operating devices connected with said local circuit for operating the said contacts, and means for producing a signal when current passes over any of said branch lines.

5. A signaling system comprising a plurality of stations, a circuit for said stations divided into sections in each station, each of

said sections normally leading to ground and having a magnet, contacts to join the adjacent sections of said circuit together, a normally open local circuit in each station having an armature to be operated by the corresponding magnet, another circuit passing through said stations and having a normally open branch line in each station leading to ground and including a magnet, contacts in each station to make and break said circuit and contacts in each station to make and break said branch lines, electrically-operating devices connected with each of said local circuits and operating the said contacts, and a normally open local signaling-instrument circuit in each station having a battery and an armature to be operated by the magnet on the corresponding branch line.

6. A signaling system comprising a plurality of stations, a circuit for said station divided into sections in each station, each section normally leading to ground and having a magnet, contacts to join two of such sections together to form a through-line between two stations, another circuit passing through said stations and normally closed in each station, contacts in each station to make and break said circuit, normally open branch lines in each station leading from said circuit, contacts to make and break said branch lines, a magnet on each branch line, a signaling instrument in each station to be controlled by the magnet on the branch line, and electrically-operating devices in each station arranged to operate said contacts when current is sent over the first-mentioned circuit to break the ground from said circuit and to connect two sections of said circuit together and to break the normal circuit of the second-mentioned circuit and to establish the corresponding branch line, and to then cause the signaling instruments to operate and then break the first-mentioned circuit into sections, to break the branch circuits, and to then reestablish the circuit through the second-mentioned circuit.

7. A signaling system comprising a plurality of stations, a circuit for said stations divided into sections in each station, a second circuit for said stations normally closed in each station, electrically-operating means at each station for joining the sections of the first-mentioned circuit together and for successively opening and closing the second-mentioned circuit in each station, said means being adapted to be operated by current over either circuit.

8. A signaling system comprising a plurality of stations, a conductor 33, in each station having a magnet, a circuit for said stations divided into sections in each station, each section leading to the corresponding conductor 33, contacts to make and break the connection with said conductor, means to join two of said sections together in a station, another circuit passing through said stations and normally closed in each station, branch

connections in each station to connect said circuit with the conductor 33 thereat, a signaling instrument in each station to be caused to operate through the medium of current sent over said second-mentioned circuit, and electrically-operating devices in each station to operate said contacts, said electrically-operating devices being arranged to be operated through the medium of current sent through said magnet over either the first or second mentioned circuits.

9. In a signaling system a plurality of stations, a conductor 33, having a magnet in each station, a circuit for said stations divided into sections in each station, each section being normally connected with the conductor 33, contacts to make and break such connections, contacts to join two of such sections together in each station, electrically-operating devices in each station to be caused to operate by the action of the magnet on conductor 33 to operate the above-mentioned contacts, and a local circuit in each station having a signaling instrument, a battery and an armature, another circuit for said stations normally closed in each station, a normally open branch line in each station to be connected with said through-circuit and having a magnet to operate said armature, said electrically-operating devices serving to break said closed circuit and to join one portion thereof with said branch line, whereby the magnet on said branch line will operate the armature to close the circuit of the signaling instrument and to subsequently connect said portion of said circuit with said conductor 33.

10. In a signaling system a plurality of stations, a circuit for said stations divided into sections in each station, each section normally leading to ground and having a magnet, contacts to make and break such ground-circuit, a contact connected with the section of such circuit that leads into a station, a contact connected with the part of a circuit that leads from a station, a contact in each station to join said contacts, a normally open local circuit in each station, electrically-operating devices on each local circuit to operate said contacts, an armature for the magnet in each station arranged to make and break said local circuit, another circuit passing through said stations and a signaling instrument in each station adapted to be caused to operate by current sent over the last-mentioned circuit.

11. A subscriber selecting and signaling system comprising a plurality of stations, a conductor having three portions leading through said stations, one portion of said conductor being normally divided into sections in each station and having means to join the sections, another portion of said conductor having means for producing a signal in each station and restoring the circuits to their normal conditions, the other portion of said conductor having means to operate the devices on the two first-mentioned portions of said

conductor, and means for throwing battery upon said conductor.

12. A subscriber selecting and signaling system comprising a plurality of stations, a normally closed battery-circuit passing through said stations, another circuit for said stations divided into sections in each station, means in each station for joining two of said sections together, devices in said stations connected with the first-mentioned circuit for connecting it with the second-mentioned circuit at any station and for sending impulses through the circuit so formed to join two sections of the line together in said stations, and means for producing a signal in the selected station.

13. A subscriber selecting and signaling system comprising a plurality of stations, a normally closed battery-circuit passing through said stations, circuit-changing devices in said stations respectively connected with said battery-circuit, another circuit passing through said stations and normally closed through the respective circuit-changing devices, the second-mentioned circuit being divided into sections in each station, means in each station for joining two of said sections together, normally open contacts connected with the second-mentioned circuit adapted to be operated by the said circuit-changing devices to send impulses over said circuit, and means for producing a signal in a selected station.

14. A subscriber selecting and signaling system comprising a plurality of stations, a normally closed battery-circuit passing through said stations, circuit-changing devices in said stations respectively connected with said battery-circuit, another circuit passing through said stations and normally closed through the respective circuit-changing devices, the second-mentioned circuit being divided into sections in each station, means in each station for joining two of said sections together, the circuit-changing devices having means for breaking the second-mentioned circuit and for connecting it with said battery-circuit, normally open contacts connected with the second-mentioned circuit and means comprised in said circuit-changing devices for operating said contacts to send impulses over said second-mentioned circuit, and means for producing a signal in a selected station.

15. A subscriber selecting and signaling system comprising a plurality of stations, a normally closed battery-circuit passing through said stations, circuit-changing devices in said stations respectively connected with said battery-circuit, another circuit passing through said stations and normally closed through the respective circuit-changing devices, one portion of the second-mentioned circuit being divided into sections in each station, means in each station for joining two of said sections together, normally open contacts connected with the second-mentioned circuit adapted to be operated by the said

circuit-changing devices to send impulses over that portion of the said circuit, the other portion of said circuit having contacts to be operated by said circuit-changing devices to send impulses thereover, and signal-producing means in said stations to be caused to operate by said last-mentioned impulses.

16. A subscriber selecting and signaling system comprising a plurality of stations, a normally closed battery-circuit passing through said stations, circuit-changing devices in said stations respectively connected with said battery-circuit, another circuit passing through said stations and normally closed through the respective circuit-changing devices, the second-mentioned circuit having a portion divided into sections in each station, means in each station for joining two of said sections together, normally open contacts connected with the second-mentioned circuit and adapted to be operated by the said circuit-changing devices to send impulses over said circuit, the other portion of said circuit having contacts to be operated by said circuit-changing devices to send impulses thereover, signal-producing means in said stations to be caused to operate by said last-mentioned impulses, and means to be operated by other impulses sent over the second-mentioned portion of the second-mentioned circuit to restore the devices that have been operated by the first-mentioned portion of said circuit.

17. A subscriber selecting and signaling system comprising a plurality of stations, a normally closed battery-circuit passing through said stations, another circuit for said stations divided into sections in each station, circuit-changing devices in each station connected with the first-mentioned circuit, the second-mentioned circuit being normally closed in said circuit-changing devices, a switch, contacts and connections comprised in said circuit-changing devices adapted to break the second-mentioned circuit and to connect it with the first-mentioned circuit when said switch is operated, and contacts connected with the second-mentioned circuit to be operated by said circuit-changing devices to send impulses over said circuit.

18. In a subscriber selecting and signaling system a plurality of stations, a normally closed battery-circuit, circuit-changing devices in each station connected with said battery-circuit, a line conductor passing through said stations in three directions, one portion of said conductor being normally divided into sections in each station, electrically-operating devices in each station for joining two of such sections together, signal-producing devices in each station, electrically-operating devices in each station connected with the portion of said conductor that passes in a direction opposite to the sectional portion for causing the signal-producing devices to operate, two contacts also connected with said conductor in each station, and two contacts in electrical connection with the mechanism

of said circuit-changing devices, whereby said contacts are arranged in pairs, and means comprised in said circuit-changing devices for operating said pairs of contacts independently 5 to direct current over said conductor in opposite directions.

19. In a subscriber selecting and signaling system a plurality of stations, a battery-circuit passing through said stations, a subscriber-selecting circuit for said stations, a signal-producing circuit for said stations, circuit-changing devices in each station arranged to connect said battery-circuit with the other two circuits and to transmit impulses over 15 said selecting and signaling circuits, and means in each station arranged to stop the operation of the circuit-changing devices by an interfering subscriber.

20. In a subscriber selecting and signaling system a plurality of stations, a battery-circuit passing through said stations, a subscriber-selecting circuit for said stations, a signal-producing circuit for said stations, circuit-changing devices in each station arranged to 25 connect said battery-circuit with the other two circuits and to transmit impulses over said selecting and signaling circuits, a magnet in each station connected with the battery-circuit, and electrically-operating devices controlled by said magnet for checking the operation of the circuit-changing devices by an interfering subscriber.

21. In a subscriber selecting and signaling system a plurality of stations, a battery-circuit 35 passing through said stations, a subscriber-selecting circuit for said stations, a signal-producing circuit for said stations, circuit-changing devices in each station arranged to connect said battery-circuit with the other 40 two circuits and to transmit impulses over said selecting and signaling circuits, a magnet in each station connected with the battery-circuit, a shunt around said magnet normally held closed by the circuit-changing devices and adapted to be broken upon the operation of the latter, and electrically-operating devices controlled by said magnet for checking the operation of the circuit-changing devices by an interfering subscriber.

50. 22. In a subscriber selecting and signaling system a plurality of stations, a battery-circuit passing through said stations, a subscriber-selecting circuit for said stations, a signal-producing circuit for said stations, circuit-changing devices in each station arranged to 55 connect said battery-circuit with the other two circuits and to transmit impulses over said selecting and signaling circuits, a magnet in each station connected with the battery-circuit, a shunt around said magnet normally held closed by the circuit-changing devices and adapted to be broken upon the operation of the latter, a normally open local circuit in each station having an armature to be operated by said magnet to close said circuit, a magnet in said local circuit, an armature therefor and a detent to be operated by

1 said armature to check the operation of the circuit-changing devices by an interfering subscriber.

23. In a subscriber selecting and signaling system a plurality of stations, a circuit for said stations divided into sections, the section of said circuit leading into a station being normally connected to ground, contacts to make 75 and break the corresponding section, normally open contacts in each station adapted to join the two sections together, a rotative drum carrying said contacts, electrically-operating devices in each station for actuating 80 said drum, and means in each station on a portion of the section that leads into a station for causing said devices to operate, a signal-producing device in each station and a circuit for said stations adapted to cause said signal-producing devices to operate.

24. In a subscriber selecting and signaling system a plurality of stations, a circuit for said stations divided into sections in each station, the section of said circuit leading into 90 a station being normally connected to ground, contacts to make and break the corresponding section, normally open contacts in each station adapted to join two sections together, a rotative drum carrying said contacts, electrically-operating devices in each station for actuating 95 said drum, and means in each station on a portion of the section that leads into a station for causing said devices to operate, a signal-producing device in each station, 100 and a circuit for said stations adapted to cause said signal-producing device to operate, and means in each station to be operated by current on the last-mentioned circuit to give 105 said drum final movement to restore the contacts to their normal positions.

25. In a subscriber selecting and signaling system a plurality of stations, a circuit for said stations divided into sections, the section of said circuit leading into a station being normally connected to ground, contacts to make and break the corresponding section, normally open contacts in each station adapted to join two sections together, a rotative drum carrying said contacts, a magnet on the portion of 115 a section that leads into a station, a normally open local circuit in each station having contacts to be joined by said magnet, a magnet and armature on said local circuit, said armature being connected with said drum to 120 operate the same, another circuit for said stations, signal-producing devices in each station adapted to be caused to operate by current on the last-mentioned circuit, and means in each station to bring the drum to 125 its normal position by means of current on the last-mentioned circuit.

26. In a subscriber selecting and signaling system a plurality of stations, a circuit for said stations divided into sections, the section of 130 said circuit leading into a station being normally connected to ground, contacts to make and break the corresponding section, normally open contacts in each station adapted to join

- two sections together, a rotative drum carrying said contacts, a magnet on the portion of a section that leads into a station, a normally open local circuit in each station having contacts to be joined by said magnet, a magnet on said local circuit, a spring-actuated armature for said magnet, connections between said armature and said drum adapted to move said drum step by step in one direction through the reciprocal action of said armature, another circuit for said stations, the signal-producing devices in said stations adapted to operate by current on the last-mentioned circuit.
- 15 27. In a subscriber selecting and signaling system a plurality of stations, a circuit for said stations divided into sections in each station, each section normally leading to ground, contacts in each station for making and breaking the corresponding sections, a drum carrying the contacts, another contact connected with a part of a section leading into a station, a contact connected with the part of a section leading from a station, a contact carried by said drum to join two contacts electrically, the positions of said contacts on said drum being such as to break the part of a section leading into a station and to join it with the part of a section leading from a station,
- 20 30 a normally open local circuit in each station having contacts, a magnet on the portion of a section leading into a station to close said contacts, another circuit for said stations, signal-producing devices in each station and electrically-operating devices in each station to be connected with the last-mentioned circuit and controlled by the action of said drum for causing said signal-producing devices to operate.
- 25 40 28. In a subscriber selecting and signaling system a plurality of stations, a circuit for said stations divided into sections in each station, contacts in each station for breaking the corresponding section and for joining two sections together, a drum carrying said contacts, electrically-operating devices in each station for operating said drum controlled by current over said circuit, another normally closed circuit for said stations, contacts in said circuit controlled by said drum for making and breaking the circuit, another contact in each station connected with said circuit, a branch line in each station having a magnet and a contact, a contact carried by said drum to join the last-mentioned contacts, and signal-producing devices in each station to be caused to operate by said magnet when the second-mentioned circuit is broken and the branch line connected therewith in a station, and means in each station for moving said drum to restore its contacts to their normal positions.
- 30 45 50 55 60 65 29. In a subscriber selecting and signaling system a plurality of stations, a circuit for said stations divided into sections in each station, contacts in each station for breaking the corresponding section and joining two sections together, a drum carrying said contacts, elec-

trically-operating devices in each station for operating said drum controlled by current over said circuit, another normally closed circuit for said stations, contacts in said circuit controlled by said drum for making and breaking the circuit, another contact in each station connected with said circuit, a branch line in each station having a magnet and a contact, a contact carried by said drum to join the last-mentioned contacts, a normally open local circuit in each station having a signaling instrument, a battery and contacts to be closed by the corresponding magnet, and means in each station to operate said drum to restore its contacts to their normal positions.

30. A telephone system comprising a plurality of conductors, means for selecting and maintaining connection with an idle conductor, and automatic means for selecting the said selected conductor to establish a circuit over the same.

31. A telephone system comprising a plurality of conductors and independent sets of electrically-operating devices arranged so that one set of the devices will select an idle conductor and maintain connection with the same to enable another set of said devices to select and establish a circuit with the said selected conductor.

32. A telephone system comprising a plurality of conductors and independent sets of electrically-operating devices arranged so that one set of the devices will select an idle conductor and maintain connection with the same to enable another set of said devices to select and establish a circuit with the said selected conductor, and whereby when the first-mentioned set of devices are disconnected from said conductor they will next disregard the said selected conductor and select and maintain connection with another idle conductor.

33. A telephone system comprising a plurality of conductors, means to select and maintain connection with one of said conductors, a telephone instrument, means for connecting the telephone instrument with said conductor, and means for another telephone instrument to select and maintain connection with the same conductor.

34. A telephone system comprising a plurality of conductors, a movable arm or contact adapted to make connection therewith, electrically-operating devices adapted to stop said arm or contact in connection with an idle conductor and to allow said arm or contact to travel when it meets a conductor that is in use, another movable arm to make connection with any of said conductors, and electrically-operating devices arranged to cause the last-mentioned arm or contact to stop in connection with a conductor that has been selected by the first-mentioned arm or contact and to disregard conductors that are not so selected.

35. A telephone system comprising a plu-

rality of conductors, a plurality of telephone instruments, means for selecting a pair of idle conductors to connect them with one telephone, and means for automatically selecting the said pair of conductors to connect them with another telephone, whereby two telephones will be connected together in a closed metallic circuit.

36. A telephone system comprising a plurality of conductors, a plurality of telephone instruments, an arm and contacts for each telephone adapted to connect a pair of idle conductors, electrically-operating devices to cause said arm to select such pair of idle conductors, and electrically-operating devices arranged to cause the arm of another telephone to select the same pair of conductors whereby two telephones may be connected through a closed metallic circuit.

37. A telephone system comprising a plurality of conductors, a plurality of telephone instruments, contacts connected with said conductors and arranged in pairs, an arm for each of the telephone instruments, contacts to be operated by the arms to join pairs of the first-mentioned contacts electrically, electrically-operating devices arranged to stop an arm to join a pair of conductors through the corresponding telephone instruments, and electrically-operating devices arranged to stop the arm of the other telephone instrument to join the contacts that are connected with the pair of conductors previously joined through the corresponding telephone instruments.

38. A telephone system comprising a plurality of conductors, a plurality of contacts connected with each conductor, said contacts being arranged in pairs, means to join a pair of said contacts together through a telephone, electrically-operating devices to hold said contacts connected, and electrically-operating devices to cause another pair of said contacts to be connected through another telephone, whereby two telephones may be connected through a closed metallic circuit.

39. A telephone system comprising a plurality of conductors, a plurality of telephone instruments, contacts connected with each of said conductors for each of said telephone instruments, another contact for use in connection with the first-mentioned contacts, an arm carrying contacts to connect a pair of the first-mentioned contacts with the telephone, one of the contacts carried by the arm being connected with the corresponding telephone, other conductors to connect the telephone with the first-mentioned contacts, electrically-operating devices arranged to stop said arm when its contacts have joined a pair of idle conductors, and electrically-operating devices arranged to stop an arm when its contacts have selected the same pair of conductors that the other arm selected, whereby two telephones may be connected in a closed metallic circuit.

40. A telephone system comprising a plu-

rality of conductors, a plurality of telephone instruments, means for selecting a pair of said conductors to join them with one of said telephones, a subscriber-selecting circuit, a circuit and devices for producing a signal for the selected-subscriber's telephone, means for connecting a called-subscriber's telephone with the selected pair of conductors, including a circuit and devices controlled by the signal-producing circuit for causing the said pair of selected conductors to be selected by a called-subscriber's devices.

41. A telephone system comprising a plurality of stations, a plurality of conductors for said stations, telephone instruments for said stations, a contact in each station connected with each conductor, a contact for connection with the corresponding telephone, movable contacts adapted to join the last-mentioned contact with a pair of contacts through a telephone, one of said movable contacts being connected with the corresponding telephone, means for operating said movable contacts, electrically-operating devices for stopping the movable contacts upon the contacts connected with a pair of conductors, electrically-operating devices arranged to cause the movable contacts connected with another telephone to select the contacts connected with the selected pair of conductors, means for producing a signal in any station, and means controlled by the call-producing devices for causing the movable contacts in a called station to select the pair of conductors that were selected at a calling-station.

42. A telephone system comprising a plurality of conductors, a plurality of telephone instruments, means for joining a telephone with a pair of said conductors, electrically-operating devices for each telephone arranged to cause the devices that join a pair of conductors through a telephone to disregard a pair of such conductors that are in use so as to connect only a pair of idle conductors through a telephone, electrically-operating devices for each telephone arranged to cause the conductor-selecting devices to only select the pair of conductors that have been selected by a calling subscriber, and means for producing a call for each telephone.

43. In a telephone system a plurality of conductors, a plurality of telephones, a contact connected with each conductor for each telephone, movable contacts for each telephone and connections between a telephone and certain of the said contacts whereby a telephone may be connected with a pair of said conductors, electrically-operating devices for causing the movable contacts to disregard a pair of conductors that are in use and to select only a pair of idle conductors, and electrically-operating devices to cause the movable contacts of another telephone to disregard idle conductors and to select only the pair of conductors that have been joined with another telephone.

44. A telephone system comprising a plu-

rality of stations, a plurality of conductors therefor, telephone instruments in each station, a contact in each station connected with each conductor, another independent contact 5 adjacent to said contacts for connection with the corresponding telephone, movable contacts to engage the pairs of contacts and the independent contact, one of the movable contacts being electrically connected with the 10 corresponding telephone, electrically-operating devices, a circuit therefor adapted to be closed during the operation of said movable contacts to stop the movable contacts upon the contacts that are connected with a pair 15 of idle conductors, and an electric circuit and devices arranged to break the last-mentioned circuit when the movable contacts pass over a pair of contacts connected with conductors that are in use to prevent the 20 movable contacts from selecting such occupied conductors, and electrically-operating devices to cause the movable contacts connected with another telephone to select the same pair of conductors that have been selected at a calling-station, and means for producing a call in a station.

45. In a telephone system a plurality of conductors, a contact connected with each conductor, a telephone instrument, an independent contact, a branch leading therefrom to ground, a branch leading from the telephone to an open contact, means for breaking the first-mentioned branch and for connecting it with the second-mentioned branch, a movable 30 arm carrying contacts adapted to engage a pair of contacts and the independent contact, one of the contacts connected with said arm being connected with the telephone, electrically-operating devices to check the movement 35 of said arm, means to control the movement of said devices during the movement of said arm, and means to prevent the operation of said devices when the movable contacts engage a pair of contacts connected with conductors that are in use.

46. In a telephone system a plurality of conductors, a contact connected with each conductor, said contacts being arranged in pairs, a telephone instrument, an independent contact, a branch leading therefrom to ground, a branch leading from the telephone to an open contact connected therewith, means for breaking the first-mentioned branch and for connecting it with the second-mentioned branch, a movable arm carrying contacts adapted to engage a pair of contacts and the independent contact, one of the contacts connected with said arm being connected with the telephone, a normally open circuit having electrically-operating devices to check the movement of said arm, means to close said circuit upon and during the movement of said arm, and means to break the last-mentioned circuit when the movable contacts engage a pair of contacts connected with conductors that are in use.

47. In a telephone system a plurality of con-

ductors, a contact connected with each conductor, a telephone instrument, an independent contact, a branch leading therefrom to ground, a branch leading from the telephone to an open contact, means for breaking the first-mentioned branch and for connecting it with the second-mentioned branch, a movable arm carrying contacts adapted to engage a pair of contacts and the independent contact, one of the contacts connected with said arm being connected with the telephone, a normally open circuit having electrically-operating devices to check the movement of said arm, means to close said circuit upon and during the movement of said arm, means to break the last-mentioned circuit when the movable contacts engage a pair of contacts connected with conductors that are in use, and means to cause the arm to stop only when its contacts engage a pair of conductors that have been selected by another arm.

48. In a telephone system a plurality of conductors, a contact connected with each conductor, a telephone instrument, an independent contact, electrical devices to join said contact with the telephone, a movable arm carrying contacts adapted to engage a pair of contacts and the independent contact, one of the contacts connected with said arm being connected with the telephone, a normally open circuit having electrically-operating devices to check the movement of said arm, means to close said circuit upon and during the movement of said arm, means to break the last-mentioned circuit when the movable contacts engage a pair of contacts connected with conductors that are in use, said normally open circuit having a contact and an armature to make and break it, a magnet for said armature, and a circuit for said armature connected with one of the movable contacts, whereby when the movable contact reaches a contact connected with a conductor that is in use said armature will break the said normally open circuit to prevent its devices from stopping the arm.

49. In a telephone system a plurality of conductors, a contact connected with each conductor, a telephone instrument, an independent contact, electrical devices to join said contact with the telephone, a movable arm carrying contacts adapted to engage a pair of contacts and the independent contact, one of the contacts connected with said arm being connected with the telephone, a normally open circuit having electrically-operating devices to check the movement of said arm, means to close said circuit upon and during the movement of said arm and means to break the last-mentioned circuit when the movable contacts engage a pair of contacts connected with conductors that are busy, said normally open circuit having a contact and an armature to make and break it, a magnet for said armature, a circuit for said armature connected with one of the movable contacts,

whereby when the movable contact reaches a contact connected with a conductor that is in use said armature will break the said normally open circuit to prevent its devices from 5 stopping the arm, and means to cause the arm to stop when its contacts engage a pair of contacts that have been selected by another arm.

50. In a telephone system a plurality of conductors, a contact connected with each conductor, a telephone instrument, an independent contact, a branch leading therefrom to ground, a branch leading from the telephone to an open contact connected therewith, means 10 for breaking the first-mentioned branch and connecting it with the second - mentioned branch, a movable arm carrying contacts adapted to engage a pair of contacts and the independent contact, one of the contacts connected with said arm being connected with 15 the telephone, a normally open circuit having electrically-operating devices to check the movement of said arm, contacts in said circuit, said circuit also having a contact and armature, a magnet for said armature, a circuit for said magnet adapted to be energized through the action of said arm, another circuit having a magnet 122, and devices to be operated by magnet 122, to break the circuit. 20

51. In a telephone system a plurality of conductors, a contact connected with each conductor, a telephone instrument, an independent contact, a branch leading therefrom to ground, a branch leading from the telephone to an open contact connected therewith, means 35 for breaking the first-mentioned branch and connecting it with the second - mentioned branch, a movable arm carrying contacts adapted to engage a pair of contacts and the independent contact, one of the contacts connected with said arm being connected with the telephone, a normally open circuit having electrically-operating devices to check 40 the movement of said arm, contacts in said circuit, one of said circuits being connected with said arm, said circuit also having a contact and armature, a magnet for said armature, a circuit for said magnet adapted to be energized through the action of said arm, another 45 normally open circuit having a magnet 122, a contact 138 connected with the movable arm to close the circuit of magnet 122, said circuit also having a contact and an armature normally disconnected, another circuit having a magnet to operate said armature, means for closing the latter circuit, and devices operated by magnet 122, for breaking the circuit through contact 138 and the 50 circuit of the third-mentioned magnet and for breaking the branch from the independent contact and connecting the said branch with the telephone.

52. In a telephone system a plurality of conductors, a contact connected with each conductor, a telephone instrument, an independent contact, a branch leading therefrom to

ground, a branch leading from the telephone to an open contact connected therewith, means for breaking the first-mentioned branch and connecting it with the second - mentioned branch, a movable arm carrying contacts adapted to engage a pair of contacts and the independent contact, one of the contacts connected with said arm being connected with the telephone, a normally open circuit having electrically-operating devices to check the movement of said arm, contacts in said circuit, said circuit also having a contact and armature, a magnet for said armature, a circuit for said magnet adapted to be energized through the action of said arm, another circuit having a magnet 122, devices to be operated by magnet 122 to break the circuit, and means for producing a signal, said means being connected with the circuit of magnet 122, whereby when the signal is produced said magnet will be energized. 75 80 85

53. In a telephone system a plurality of conductors, a contact connected with each conductor, a telephone instrument, an independent contact, a branch leading therefrom to ground, said branch having contacts 88, 88^a, and 119, a rotative drum carrying the contact 88^a, said drum also being arranged to have 90 longitudinal movement, a telephone, a contact connected therewith and adapted to be connected with contact 88, an arm connected to rotate with said drum, contacts operated by said arm to connect a pair of contacts and the independent contact, one of the contacts operated by the arm being connected with the telephone, a magnet and devices connected therewith to check the movement of said arm and the drum, a normally open circuit 95 for said magnet, contacts for said circuit, a contact 104, carried by the drum to close said circuit, said circuit also having an armature and contact to break it, another circuit having a magnet 117 to operate said armature to 100 break the circuit of magnet 101 to cause it to stop the rotation of said arm and drum, and means to energize magnet 117, as and for the purpose specified. 105 110 115

54. A telephone system comprising a plurality of stations, a plurality of conductors therefor, a telephone in each station, signal-producing instruments in each station, a circuit for said stations to cause said signal-producing instruments to operate, electrically-operating devices in each station to connect a pair of said conductors with the telephone, means in each station to be operated by the signal-producing devices thereat to set the devices in a called station in position to 120 enable a pair of conductors to be selected and to join the corresponding telephone with said conductors, electrically-operating devices to cause a pair of said conductors to be selected in the calling-station, and means in each station arranged to be operated in the calling-station by the devices in the called station for connecting the telephone in the calling-station with the selected pair of conductors 125 130 135

- to finally join the telephones in a calling and a called station in a closed metallic circuit.
55. A telephone system comprising a plurality of stations and a plurality of conductors, a contact connected with each conductor in each station, a telephone in each station, a drum and an arm connected therewith in each station, contacts operated by said arm and connections from the telephone to be joined by said arm with a pair of said contacts, a magnet 101 and devices to be operated thereby to check the movement of said arm and drum, a circuit for said magnet controlled by a contact carried by said drum, a magnet 122 having two circuits, signal-producing instruments in each station, one of the circuits of magnet 122 being connected with said signal-producing instruments, whereby said magnet will cause the drum to be moved longitudinally upon a call being produced, the other circuit of magnet 122, having a contact to open and close it, said contact being carried by the corresponding drum, and means for energizing magnet 122, through its second-mentioned circuit to also cause it to move the drum longitudinally.
56. A circuit-controller comprising a toothed wheel, contacts carried thereby and insulated therefrom, contact-fingers respectively engaging said contacts, a switch carried by and insulated from said wheel and electrically connected with one of said contacts, a contact in electrical engagement with said wheel to be engaged by said switch, a switch 20, also insulated from and carried by said wheel, said switch being connected with another of said contacts, a contact 21, for engagement with switch 20, and electrically connected with another of said contacts carried by the wheel, and means for moving said switches to make and break circuits through the first-mentioned contacts.
57. A circuit-controller comprising a toothed wheel, contacts carried thereby and insulated therefrom, contact-fingers respectively engaging said contacts, a switch carried by and insulated from said wheel and electrically connected with one of said contacts, a contact in electrical engagement with said wheel to be engaged by said switch, a switch 20 also insulated from and carried by said wheel, said switch being connected with another of said contacts, a contact 21, for engagement with switch 20, and electrically connected with another of said contacts carried by the wheel, said switches being connected together, a stationary stop and an adjustable stop for moving one of said switches to make and break circuits through the first-mentioned contacts.
58. A circuit-controller comprising a toothed wheel, contacts carried thereby and insulated therefrom, contact-fingers respectively engaging said contacts, a switch carried by and insulated from said wheel and electrically connected with one of said contacts, a contact in electrical engagement with said wheel to be engaged by said switch, a switch 20 also insulated from and carried by said wheel, said switch being connected with another of said contacts, a contact 21, for engagement with switch 20, and electrically connected with another of said contacts carried by the wheel, said switches being connected together, a contact 21 for engagement with switch 20, and electrically connected with another of said contacts carried by the wheel, means for moving said switch to make and break circuits through the first-mentioned contacts, a handle connected with said wheel, and a train of gearing also connected with said wheel for moving the latter in the reverse direction to its movement by the handle.
59. A circuit-controller comprising a toothed wheel, a presser carried by said wheel, contacts adapted to be held in normal engagement by said presser, and electrically-operating devices controlled through said contacts to check the movement of said wheel.
60. A circuit-controller comprising a toothed wheel, a presser carried by said wheel, and contacts adapted to be held in normal engagement by said presser, a detent to check the movement of said wheel, and a magnet and armature to operate said detent.
61. A circuit-controller comprising a frame having a plurality of apertures, a toothed wheel mounted in said frame, contacts carried by said wheel and insulated therefrom, contact-fingers respectively engaging said contacts, two switches connected with two of said contacts and carried by and insulated from said wheel, a contact 21 carried by and insulated from said wheel and connected with the other of said contacts, a stop or plug to operate said switches, said switches being connected together, a contact 10 connected with said wheel for engagement with one of said switches, a pair of supplemental teeth carried by said wheel, rocker-arms to be operated by the teeth, and a pair of contacts for each of said rocker-arms to be made and broken thereby.
62. A circuit-controller comprising a frame having a plurality of apertures, a toothed wheel mounted in said frame, contacts carried by said wheel and insulated therefrom, contact-fingers respectively engaging said contacts, two switches carried by and insulated from said wheel connected with two of said contacts, a contact 21, connected with the other of said contacts and carried by and insulated from said wheel, a stop and a plug to operate said switches, said switches being connected together, a contact 10, connected with said wheel for engagement with one of said switches, a pair of supplemental teeth carried by said wheel, rocker-arms to be operated by the teeth, a pair of contacts for each of said rocker-arms to be made and broken thereby, a presser carried by said wheel, a pair of contacts normally closed by said presser, and electrically-operating devices for checking the movement of said wheel in one direction.
63. A circuit-controller comprising a frame having a plurality of apertures, a toothed wheel mounted in said frame, contacts carried by said wheel and insulated therefrom, con-

tact-fingers respectively engaging said contacts, two switches carried by and insulated from said wheel connected with two of said contacts, a contact 21, connected with the other of said contacts and carried by and insulated from said wheel, a stop and a plug to operate said switches, said switches being connected together, a contact 10, connected with said wheel for engagement with one of said switches, a pair of supplemental teeth carried by said wheel, rocker-arms to be operated by said teeth, a pair of contacts for each of said rocker-arms to be made and broken thereby, a presser carried by said wheel, a circuit having a pair of contacts normally closed by said presser, a detent to check the movement of said wheel, a magnet on said circuit, and an armature to operate said detent.

64. A circuit-controller comprising a frame having a plurality of apertures, a stop-plug to enter said apertures, a toothed wheel carried by said frame, means for operating said wheel, supplemental teeth carried by said wheel, a plurality of concentric annular contacts carried by and insulated from said wheel, contact-fingers to respectively engage said annular contacts and carried by and insulated from said frame, a switch 9, carried by and insulated from said wheel and connected with one annular contact, a switch 20 carried by and insulated from said wheel and connected with another annular contact, said switches being connected together, a contact 10, for one switch electrically connected with said wheel, a contact 21, for the other switch insulated from said wheel, said contact being connected with the remaining annular contact, rocker-arms to be operated by the teeth of said wheel and by the supplemental teeth, and contacts to be operated by said rocker-arms.

65. A circuit-controller comprising a frame having a plurality of apertures, a stop-plug to enter said apertures, a toothed wheel carried by said frame, means for operating said wheel, supplemental teeth carried by said wheel, a plurality of concentric annular contacts carried by and insulated from said wheel, contact-fingers to respectively engage said annular contacts and carried by and insulated from said frame, a switch 9, carried by and insulated from said wheel and connected with one annular contact, a switch 20, carried by and insulated from said wheel and connected with another annular contact, said switches being connected together, a contact 10 for one switch electrically connected with said wheel, a contact 21, for the other switch insulated from said wheel, said contact being connected with the remaining annular contact, rocker-arms to be operated by the teeth of said wheel and by the supplemental teeth, contacts to be operated by said rocker-arms, a presser carried by said wheel, contacts normally closed by said presser, and electrically-operating de-

vices to check the movement of said wheel in one direction.

66. The combination of a rotative shaft, a pivoted arm, means for moving said arm by said shaft in one direction and for allowing said shaft to have movement independent of said arm in the other direction, and electrically-operating devices for checking the movement of said arm. 70

67. The combination of a rotative shaft, a pivoted arm, means for moving said arm by said shaft in one direction and for allowing said shaft to have movement independent of said arm in the other direction, and electrically-operating devices for checking the movement of said arm. 75

68. The combination of a rotative shaft, a drum carried thereby to turn therewith and adapted to have longitudinal movement thereon, electrically-operating devices for moving said drum longitudinally in one direction, means for moving said drum longitudinally in the opposite direction, a pivoted arm, means for moving said arm by said shaft in one direction and for allowing said shaft to have movement independent of said arm in the other direction, and electrically-operating devices for checking the movement of said arm. 80

69. The combination of a rotative shaft, a pivoted arm, a projection carried by said shaft to move said arm in one direction, and electrically-operating devices for checking the movement of said arm. 95

70. The combination of a rotative shaft, a telephone-supporting arm, gearing between the latter arm and said shaft whereby said arm may rotate said shaft, a pivoted circuit-controlling arm, and connections between said shaft and the latter arm for moving said arm by said shaft in one direction. 100

71. The combination of a rotative shaft, a drum carried thereby to turn therewith, a telephone-supporting arm, gearing between the latter arm and said shaft whereby said arm may rotate said shaft, a pivoted circuit-controlling arm, connections between said shaft and the latter arm for moving said arm by said shaft in one direction, electrically-operating devices for moving said drum longitudinally on said shaft, and means for moving the drum in the opposite direction. 110

72. The combination of a rotative shaft, a drum carried thereby to turn therewith, a telephone-supporting arm, gearing between said arm and said shaft, said gearing having means to allow the shaft to move independently of said arm in one direction, a pivoted circuit-controlling arm, means carried by said shaft for moving the latter arm in one direction, electrically-operating devices for moving said drum longitudinally in one direction, and means for moving said drum in the opposite direction. 120

73. The combination of a rotative shaft, a telephone-supporting arm, gearing between

5 said arm and said shaft, said gearing having a pin or projection 157, an arm 156, to engage one side of said pin, a pivoted circuit-controlling arm, and a projection carried by said shaft to move said arm in one direction.

74. The combination of a rotative shaft, an arm 94, pivotally carried by said shaft, a projection 150, carried by said shaft to move said arm in one direction, a telephone-supporting 10 arm, and gearing connecting the latter arm with said shaft.

75. The combination of a rotative shaft, an arm 94, pivotally carried by said shaft, a projection 150, carried by said shaft to move said 15 arm in one direction, a spring interposed between the arm 94, and the shaft, a telephone-supporting arm, and gearing between the latter arm and said shaft.

76. The combination of a rotative shaft, an 20 arm 94, independent of said shaft, means connected with said shaft for moving said arm in one direction, teeth connected with said arm, a detent to engage said teeth to stop the movement of said arm, and a magnet and armature to operate said detent, whereby said 25 shaft can continue to move when the arm is stopped.

77. The combination of a rotative shaft, a drum carried thereby to turn therewith and adapted to have longitudinal movement thereon, contacts carried by said drum, contact-fingers to engage said contacts, and means for moving said drum longitudinally in two directions to change the circuits through said fingers and contacts. 30

78. The combination of a rotative shaft, a pivoted arm 94, means for moving said arm by said shaft in one direction, a telephone-supporting arm, gearing between the latter arm and said shaft, a projection carried by 40 the telephone-arm, and contacts to be made and broken by said projection.

79. A circuit-controlling device comprising a pair of contacts, an arm carrying the same, other pairs of contacts, a rack connected with 45 said arm, a magnet, a circuit therefor controlled by the last-named contacts, a catch to be controlled by said magnet, and means controlled by said catch to engage and stop said rack and arm.

CHAS. B. SMITH.
